UNITED STATES PATENT OFFICE

RUDOLPH FRANK STEHLIK, OF CHICAGO, ILLINOIS, ASSIGNOR TO RESERVE HOLDING COMPANY, OF KANSAS CITY, MISSOURI, A CORPORATION OF DELAWARE

AUTOMATIC TELEPHONE SYSTEM

Application filed May 14, 1928, Serial No. 277,525, and in Belgium October 8, 1927.

The present invention relates to improvements in or relating to automatic telephone systems and more particularly concerns small exchange systems such as are used in private offices or in villages or the like.

One of the objects of the present invention is to provide a small exchange system having a capacity of up to five or ten speaking circuits and employing only line switches and 10 relays.

According to one feature of the present invention the line switches of the calling and called lines are set and operated to establish connection with the same relay group, the 15 called line switch being operated over leads all of which are common to other line switches.

The line switches according to this feature of the invention may be either of the rotary 20 type in which the wipers are operated step by step over a single level by a pawl and ratchet mechanism or of the plunger type and it is believed to be novel to employ line switches in this manner.

Another feature of the invention relates to a relay counting and storage arrangement in which the tens digit is first counted on a set of counting relays less in number than the maximum number of impulses in a series to be 25 counted and then transferred to the storage relays which are also less in number than the maximum number of impulses in a series to be counted and then utilizing the counting relays to count the units digit; the storage 30 relays and counting relays then jointly control an operation such as the operation of a called subscriber's line switch.

Another feature of the invention relates to the setting up of calls from a small exchange 20 to a main exchange by which the trunk line is connected to the trunk relay group by different leads but in a manner similar to that in which a called subscriber's line is connected to the trunk relay group on a local call.

These and other features of the invention will be better understood by referring to the accompanying drawings, Figs. 1-15, which show by means of the usual circuit diagrams sufficient of the apparatus employed in the 45 present invention to enable the description

to be followed. It will be understood, however, that various modifications may be made in the circuit details by those skilled in the art without departing from the spirit of the invention.

Referring now to the accompanying drawings, Fig. 1 shows the line switch of a subscriber 22 together with the bank of ten sets of contacts that are available for the plunger arm of his line switch to operate. The lower 60 part of the figure shows the circuit of the master switch which is used to control the alignment of the free plunger arms of the line switches of all the subscribers. The plungers employed are of the self aligning type fitted 65 with spring control so that when a plunger is released by the de-energization of a plunger magnet at the end of a conversation, it is automatically brought into line with the remaining free plungers under the control of 70 the master switch.

Fig. 2 shows a battery feed relay group shown in connection with the line switch of subscriber 22 in Fig. 1; similar relay groups are represented by rectangles marked TRG 75 2-5 in Fig. 1.

Fig. 3 shows the line switches of subscribers 52 and 56 so that the operation of the master switch in conjunction with the line switches may be more easily followed.

Fig. 4 shows one of the two recorders in which the chain of counting relays shown in the top left-hand corner is used first to count the tens digit; this digit is then transferred to the storage relays W, X, Y, Z, and the 85 counting relays are then used to count the units digit.

Fig. 5 shows the marker, the seven tens marking relays being shown on the left-hand side and the units marking relay on the right- 90 hand side.

Fig. 6 shows a general layout of another modification of the invention employing rotary line switches.

Fig. 7 shows calling and called subscriber's 95 line switches.

Fig. 8 shows a trunk relay group.

Fig. 9 shows a recorder and recorder finder.

Fig. 10 shows a main trunk relay group 100

used in connection with calls incoming from and outgoing to the main exchange.

Fig. 11 shows a battery feed group used for converting the ordinary subscriber's impulses into battery impulses.

Fig. 12 is a trunking diagram of connections with the main exchange.

Fig. 13 shows circuit details of a trunk line switch used for setting up calls outgoing to the main exchange.

Figs. 14 and 15 show an arrangement for subscribers' line switches alternative to that shown in Figs. 1 and 3. In this case each subscriber has two line switches, one of which 15 operates on outgoing calls and the other of which operates on incoming calls.

An alternative form for exchanges having a larger capacity and permitting of two speaking circuits is described with relation 20 to Figs. 14 and 15. In this case each subscriber is provided with two line switches, for instance, subscriber No. 22 is provided with an outgoing line switch OLS22 which serves for outgoing calls and an incoming line 25 switch ILS22 which serves for incoming calls. Similarly subscriber No. 56 is provided with line switches OLS56 and ILS56. Further, subscriber No. 52 is provided with line switches OLS52 and ILS52. The line 30 switches OLS22, OLS56, OLS52 have access to the inlet ends of ten trunk relay groups such as that shown in Fig. 2, while the line switches ILS22, ILS56, have access to the outlet ends of the same trunk relay groups. 35 Two separate master switches OMS and IMS are provided; the master switch OMS controlling the outgoing switches such as OLS22, OLS56 and OLS52, while the master switch IMS controls the incoming line switches 40 ILS22, ILS56 and ILS52. The only alteration between this arrangement and that described with reference to Figs. 1, 2, 3, 4 and 5 is that the line switches are altered and Figs. 14 and 15 should be substituted for Figs. 1 45 and 3. The outgoing master switch OMS is of substantially standard construction and design, while the incoming master switch IMS has been specially designed to operate in the manner which will be described.

In order that the invention may be better understood a description will be given of the setting up of a complete connection and it will be assumed that subscriber No. 22 wishes to make connection with subscriber No. 56. 55 When subscriber No. 22 lifts his receiver to initiate a call he completes a circuit as follows; battery line relay LR22, contact 11, line 12 of the subscriber's loop through the subscriber's instrument and back over line 13, 60 contact 14 to earth. Line relay LR22 therefore picks up over this circuit and closes contact 15, whereby a circuit is completed for the pull down winding of the plunger magnet PM22 as follows; battery, upper or pull down 65 winding PDC of PM22, contact 16, contact

15, conductor DM, contact 100 to earth. That is, assuming contact 100 is closed, which it normally is except when the master switch MS is hunting, plunger magnet PM22 energizes and causes the plunger to engage with 70 the contact bank so that contacts 17, 18, 19 and 20 are closed and thereby lines 12 and 13 are connected forward to lines 21 and 22 respectively, while earth is connected over contact 19 to the contact of the bank of the

master switch corresponding to the magnet PM22 (this contact is given the reference 75 23). The closure of a circuit over contacts 17 and 18 causes a circuit to be completed over the subscriber's loop for the line relay LR in 80

the battery feed relay group Fig. 2, line relay LR energizes and at contact 25 completes a circuit for release relay RR. Release relay RR therefore energizes and closes contact 24, thereby connecting earth back over the re- 85 lease trunk 26, contact 20, lower winding BCO of the plunger magnet PM22 to battery. It should be mentioned that when magnet PM22 energized it opened contacts 11 and 14, thereby permitting LR22 to de-energize. 90

LR22 is, however, a slow to release relay and therefore does not fall away for some little time, so that contact 15 remains closed until the circuit for the lower winding of the plunger magnet has been completed. The 95 current through this winding is sufficient to hold the contacts 17, 18, 19 and 20 closed and to hold open the contacts 11 and 14. Relay RR on energizing, in addition to closing contact 24 closes contact 27, whereby a circuit is 100 completed as follows; earth, contact 27, contact 28, conductor 29, contact 30 of switching relay SR1, contact 32 of switching relay SR2, recorder test relay RTR to battery. RTR energizes and closes contacts 31 and 33, there- 105

by completing a circuit over contact 31 as follows: earth contact 34, contact 31, upper winding of relay SR2 to holding conductor 35; and a circuit over contact 33 as follows; earth on contact 36, contact 33, upper winding of relay SR1, conductor 37, relay HR1 of relay recorder group RRG1 to battery conductor 35 leads to relay recorder group RRG2. If relay recorder group 1 is busy, earth will 110 be connected directly to contact 158 over contacts in the trunk relay group which has taken RRG1 into use, similar to contacts 27 and 28 in TRG1. If relay recorder group RRG1 is busy the upper winding of SR1 is merely short-circuited when earth is connected to its 115 lower terminal by the closure of contact 33. This has no effect on relay SR1 which is locked energized at contact 157. The closure of contact 31 places earth on the lower terminal of the upper winding of relay SR2 and 120 if relay recorder group RRG2 is free, relay SR2 will energize and connect the relay recorder group RRG2 to trunk relay group TRG1. If, on the other hand, the relay re- 125

cord group RRG1 is free and RRG2 is busy, 125

130

relay SR1 will energize in series with relay HR1 over the following circuit; earth, contact 36, contact 33, upper winding of relay SR1, conductor 37, holding relay HR1 to battery; relay HR1 will energize in series with the upper winding of relay SR1 and close contact 38 and 39. At contact 38 a circuit is closed as follows: earth, contact 38, contact 81, storage connector relay SCR to battery. The operation of relay SCR, however, has no immediate effect. Relay SR1 on energizing closes a locking circuit for itself at contact 157 as follows: battery, lower winding of relay SR1, contact 157, conductor 29, contact 28, contact 27, earth. The circuit of relay RTR is broken at contact 30 and relay RTR falls back opening contacts 31 and 33, thus cutting off relay SR2. At contact 158, relay SR1 closes a maintaining circuit for relay HR1 and at contact 51 extends the impulsing conductor 43 to the relay recorder group RRG1. If, however, both RRG1 and RRG2 had been busy, then neither SR1 nor SR2 would operate and when dialling commenced the busy signal would be given to the calling subscriber in a manner which will be described later.

The subscriber now commences to dial the first digit five. In this case it will be assumed first of all that both RRG1 and RRG2 were busy. In this case as soon as the line relay LR Fig. 2 falls back a circuit would be completed as follows: earth, contact 40, contact 41, contact 42, impulsing conductor 43, contact 44, contact 45, (relays SR1 and SR2 both being de-energized), busy test conductor 46, upper winding of busy relay BR to battery. Busy relay BR accordingly energizes and locks energized over contact 47 to the release trunk 26 and at contact 48 connects up the busy tone to the conductor 49 which passes via condenser 50, conductor 22, conductor 13 to the calling subscriber's line and back over conductors 12 and 21 through the upper winding of relay LR to battery; when the subscriber listens and hears the busy tone, he knows that he cannot complete the connection.

If, however, relay recorder group RRG1 is idle a circuit will be completed on the transmission of the first impulse of the series as follows: earth, contact 40, contact 41, contact 42, conductor 43, contact 51, conductor 52, contact 53, contact 54, contact 55, contact 56, counting relay FR1 to battery. Relay FR1 accordingly energizes and closes contacts 57 and 58. A branch circuit for the first impulse also passes through change-over relay CH1, and relay CH1 accordingly energizes and closes contact 59, thereby energizing relay ACH1. Relay ACH1 energizes and closes contact 60 thereby preparing a locking circuit for relay FR1 as follows: earth, contact 60, contact 61, relay FR1A contact 57, relay FR1 to battery. This locking

circuit however is not effective until earth is removed from the upper terminal of relay FR1 over conductor 52 on the termination of the impulse. Consequently when the first impulse ends, relay FR1A energizes in this locking circuit with relay FR1, thereby opening contact 56 and closing contact 62. Relay FR1A operates other contacts the purpose of which will be clear later.

Relays CH1 and ACH1 are both slow to release and consequently remain energized during the train of impulses, and accordingly the next operation which takes place occurs on the transmission of the next impulse when relay LR de-energizes a second time. Relay LR closes a circuit which this time may be traced as follows: earth, contact 40, contact 41, contact 42, conductor 43, contact 51, conductor 52, contact 53, contact 54, contact 55, contact 62, relay FR2 to battery. Relay FR2 accordingly energizes and closes contact 63, thereby preparing a locking circuit for itself as follows: earth, contact 60, contact 64, relay FR2A, contact 63, relay FR2 to battery. This locking circuit however does not become effective until earth over conductor 52 is removed from upper terminal of relay FR2 on the termination of the impulse. When this occurs relay FR2A energizes in the locking circuit of relay FR2 and opens contact 61 thereby enabling relays FR1A and FR1 to release. At the same time it opens contact 55 and closes contact 65. The next impulse may be traced over the previously described circuit including contact 54, but this time it passes over contact 65 instead of contact 55 to relay FR3 and battery. Relay FR3 energizes, closes contact 66 whereby a locking circuit for itself is prepared as follows: earth, contact 60, contact 67, relay FR3A, contact 66, relay FR3 to battery. This, as before, only becomes effective when earth over conductor 52 is removed from the upper terminal of relay FR3, on the termination of the impulse whereupon relay FR3A energizes and opens contact 64, thereby releasing relays FR2A and FR2. At the same time relay FR3A opens contact 54 and closes contact 68. The fourth impulse may be traced over the previously described circuit, including contact 53 but instead of passing over contact 54, it now passes over contact 68, contact 69, relay FR4 to battery. Relay FR4 energizes and prepares a locking circuit for itself as follows: battery, relay FR4, contact 70, relay FR4A, to earth on contact 60. As soon as the fourth impulse terminates earth over conductor 52 is removed from the upper terminal of relay FR4, and accordingly the locking circuit becomes effective and relay FR4A energizes opening contact 69 and closing contact 71. It also opens contact 67, thereby opening the locking circuit of relays FR3A and FR3, which relays accordingly de-energizes, and closes contact 72. The fifth

impulse may be traced over the previously described circuit, including contact 52 but instead of passing over contact 51, it now passes over contact 72, contact 73, relay FR5 to battery. Relay FR5 energizes, closes contact 74 whereby a locking circuit for itself is prepared as follows: battery, relay FR5, contact 75, relay FR5A, to earth on contact 60. As soon as the fifth impulse terminates earth over conductor 52 is removed from the upper terminal of relay FR5, and accordingly the locking circuit becomes effective and relay FR5A energizes opening contact 73 and closing contact 76. It also opens contact 72, thereby opening the locking circuit of relays FR4A and FR4, which relays accordingly de-energizes, and closes contact 77. The sixth

impulse will now pass over contacts 54, 55 and 56 to relay FR1 and battery, since relays FR1A, FR2A and FR3A have restored to normal. Relay FR1 accordingly energizes, prepares a locking circuit for itself as before over contact 57, relay FR1A, contact 61, contact 60, to earth, but contact 61 is this time short-circuited by contact 72. This is of no importance seeing that at the present time we are only transmitting five impulses but the purpose of it will become apparent later when more than five impulses are generated. On the termination of the fifth impulse, relay FR1A energizes in series with relay FR1 as before. Since the fifth impulse terminates the series, relay CH1 will now de-energize. This will be followed shortly after by relay ACH1 but in the meanwhile a circuit may be traced as follows; earth contact, 73, contact 74, contact 75, contact 188, relay FR4 being energized, contact 77, relay FR1A being also energized, contact 78, conductor 79, contact 80, lower winding of relay Y, lower winding of relay Z to battery thus causing storage relays Y and Z to energize. Relays Y and Z on energizing complete locking circuits for themselves as follows; earth contact 38, contact 84, contact 83 and thence for relay Z over contact 82 and the upper winding of relay Z to battery, and for relay Y over contact 85 and the upper winding of relay Y to battery. As mentioned above, relay ACH1 de-energizes shortly after relay CH1 falls back, and consequently contact 84 opens shortly after the events just described, thereby removing a short-circuit from the disconnect relay DR so that the locking circuit for relays Y and Z instead of passing over contact 84, now passes as follows: earth, contact 38, relay DR, contacts 82 and 85 and upper windings of relays Z and Y respectively to battery. Relays Y and Z are therefore locked energized through their upper windings, relay DR energizes and opens contact 83, thereby preventing relay DR being de-energized in the next series of impulses, when contact 84 is again closed. Relay DR opens contact 81 to enable relay SCR to release and open contacts 87 to 92 inclusive; and also opens contact 75 and closes contact 86 to enable an impulse to be sent at the end of the next series over a different circuit for a purpose to be described later.

When ACH1 released it also opened contact 60, thereby opening the locking circuit of relays FR4, FR4A, FR1, FR1A, so that these relays restore to normal and everything is now in readiness for the transmission of the next series of impulses. The next series of impulses as regards Fig. 2 operate the same as before and the impulse may be traced from; earth, contact 40, contact 41, contact 42, conductor 43, contact 51, conductor 52, contact 53, contact 54, contact 55 contact 56, relay FR1 to battery, while a branch circuit also extends over relay CH1 to battery. Relay CH1 energizes as before, opens contact 73, and closes contact 59. Relay ACH1 also energizes as before and closes contacts 60, 74 and 75 and opens contact 144. At contact 60 it prepares a locking circuit for relay FR1A as follows: earth, contact 60, contact 61, relay FR1A, contact 57, relay FR1 to battery. This, however, only becomes effective at the end of the first impulse when earth is removed from the upper terminal of relay FR1. When this impulse terminates, relay FR1A energizes in series with relay FR1, opens contact 56 and closes contact 62, thereby preparing an energizing circuit for relay FR2, which as previously described energizes at the beginning of the second impulse and is locked energized in a locking circuit as follows: battery, relay FR2, contact 63, relay FR2A, contact 64, contact 60 to earth. At the end of the second impulse, relay FR2A energizes; on the third impulse relay FR3 energizes at the beginning and relay FR3A at the end as previously described; and on the fourth impulse, relay FR4 energizes at the beginning and relay FR4A at the end. As will be recollected from the previous circuit, each succeeding relay opened the locking circuit for the previously energized relay so that at the end of the fourth impulse, relays FR4 and FR4A were alone energized and these remain energized during the remainder of the impulse series. Relays FR1 and FR1A are energized at the end of the fifth impulse as previously described, relays FR4 and FR4A remaining energized. The sixth impulse may now be traced as follows: earth, contact 40, contact 41, contact 42, conductor 43, contact 51, conductor 52, contact 53, contact 54, contact 55, contact 62, relay FR2 to battery. Relay FR2 energizes and prepares a locking circuit for itself over contact 63 in series with relay FR2A, contact 64, contact 60 to earth. At the end of the sixth impulse relay FR2A energizes in series with relay FR2 in this locking circuit and opens contact 61. Relays FR1 and FR1A, however, are not de-energized since they are locked energized over contact 72 independently of contact 61. Consequently at the end of the sixth impulse relays FR2 and FR2A remain energized and the following six relays are all energized at this time: FR4, FR4A, FR2, FR2A, FR1, FR1A, and all these are dependent upon earth at contact 60. At the end of the series of impulses, relay CH1 de-energizes and is followed after an interval by the de-energization of relay ACH1 but in the interval thus produced an extensive train of operations takes place as will now be described.

Upon the de-energization of relay CH1, a circuit is completed as follows: earth, contact 73, contact 74, contact 86, relay SDR to

battery. Relay SDR accordingly energizes, opens contact 53 to prevent further impulses affecting the counting relay chain and closes a locking circuit for itself at contact 93 as follows: battery, relay SDR, contact 93, contact 39, to earth, and relay SDR therefore becomes solely dependent upon the holding relay HR1. At contact 111, relay SDR closes a circuit from battery, relay ACH1, contact 111, contact 110 to earth for maintaining the relay ACH1 energized until the master switch has completed its hunting operation as will be seen later. Relay SDR also closes contact 94, thereby connecting earth over the conductor 95 to energize the start relay SRM of the master switch. The master switch start relay SRM therefore operates and closes contact 99 thereby completing a circuit for open main relay OMR which energizes and disconnects earth at contact 100 from the open main conductor DM thereby preventing the operation of any subscriber's plunger magnet if he should remove his receiver while the master switch is hunting. At contact 96 relay SRM completes a circuit for the lower winding of the differential locking magnet as follows: earth, contact 96, lower winding of the locking magnet LM to battery. The locking magnet LM accordingly energizes and closes contact 97. At contact 97 it connects earth to relay OMR, this however is without effect since earth will be supplied at contact 99 by relay SRM which remains energized until the master switch has finished its hunting operation; contact 97 is provided for the case when the master switch is hunting for the inlet end of a free trunk relay group in which case the relay SRM is not energized. An auxiliary circuit for the upper winding of the locking magnet, which is wound in the opposite direction to the winding just energized in circuit with contact 96, is now connected in a circuit extending as follows: earth, contact 96, upper winding of locking magnet LM, contact 101, contact 102, wiper 103 of the master switch to the contact with which the wiper is engaging. This circuit is therefore dependent upon the potential at the contact on which the wiper 103 happens to be resting. The locking magnet as is well known, on energizing releases the master switch so that it moves all the idle plungers around, at the same time moving the wipers 103 and 606. Consequently as soon as the wiper 103 rests on a contact connected to battery, the windings of the locking magnet LM are energized in opposition to each other and the locking magnet de-energizes, the master switch is then locked, and the contact 97 opened. It will be seen later that the hunting operation of the master switch has taken place between the falling back of relay CH1 and the falling back of relay ACH1 and that in this interval relays SDR, SIR and FR have energized in suc-
 cession. When relay ACH1 then falls back a circuit is completed for relay SR of the trunk relay group TRG1 which in turn completes a circuit for relay COR which cuts off the relay recorder group. Relay SDR de-energizes and removes earth from conductor 95, relay SRM falls back and opens the circuit of relay OMR which releases after a short interval and closes contact 100. It will also be seen later that the operation of the plunger arm PA66 occurs at the same instant as the operation of relay FR in the relay recorder group RRG1. It is of course necessary for the master switch to set all the idle plungers adjacent to the outlet or answering end of the trunk relay group over which the call for subscriber 56 has been initiated, and battery was accordingly connected to contact 105 over conductor 104 by the operation of relay SDR at the instant of the termination of the second digit; contact 105 corresponding in position to the connection of the outlet end of the trunk relay group in the bank of the line switches. The connection of battery to conductor 104 may be traced as follows: battery, selection initiating relay SIR, contact 108, conductor 107, contact 106, conductor 104, contact 105, wiper 103, contact 102, contact 101, upper winding of differential locking magnet LM, contact 96, to earth; and since only one circuit such as that just described can be closed at a time and consequently only one relay such as SIR can be energized at a time; then assuming that the relay SIR (which, as has been described, is associated with the recorder which in turn is associated with the trunk relay group TRG1) is operated it will be seen that all the plungers have been aligned opposite the springs connected to the outlet end of the relay group TRG1 shown in Fig. 2. Relay SIR energizes over this circuit and closes contact 109 for a purpose to be described later, opens contact 110, thereby opening the maintaining circuit for relay ACH1, which had extended over contact 111. At contact 124 relay SIR closes a circuit for the units relay as will be described later, and at contact 112 closes a circuit for one of the tens relays. When relay SIR closes contact 112 a circuit is completed as follows: earth, contact 112, contact 113 of relay Z, which it will be recollect that was energized after the transmission of the first digit, contact 114 of relay Y, which was also energized, conductor 115, relay TD5 to battery. Relay TD5 is provided individual to subscribers whose first digit is five, and consequently is operated every time a subscriber having one of these numbers is called. Since, in the present example, subscriber 56 is being called, relay TD5 energizes and closes contacts 116 to 122 inclusive. Earth is connected over these contacts to each of seven conductors such as conductor 123 which receives its earth connec-

 130

tion at contact 121 and then proceeds directly to the line switch of subscriber 56; similar single conductors connect each of the other of contacts 116 to 122 inclusive to one of the line switches of subscribers whose numbers have five as their first digit.

The connection of earth to conductor 123 causes a circuit to be completed for relay UCR56 as follows: earth, contact 121, conductor 123, contact 600, winding of relay UCR56 to battery; relay UCR56 energizes, thereby opening contact 602 and closing contact 603.

It will be seen that the earth connected to conductors similar to conductor 123 closes a circuit for each of the relays such as relay UCR56, i. e. relays UCR51—55 and UCR57 provided that the corresponding line switch is not busy; if any of the line switches of subscribers 51—57 are busy the relay corresponding to relay UCR56 will be cut off at a contact corresponding to contact 600.

In the further example illustrated, viz. line switch of subscriber 52, if the line switch is idle a circuit is closed for relay UCR 52 over the following circuit; earth, contact 117, conductor 98, contact 601, relay UCR52 to battery; relay UCR52 energizes thereby opening contact 604 and closing contact 605. If the line switch had been busy the circuit of relay UCR52 would have been open at contact 601 which is maintained open during a call by the lower winding of relay PM52.

Relay SIR in addition closes contact 124, thereby completing a circuit as follows: earth, contact 124, conductor 125, units relay UR to battery; relay UR energizes and closes contacts 126 to 132, inclusive. Of these, contact 127 is connected to conductor 133 which is connected to contacts such as 603 of the relays UCR of the line switches of each of the subscribers whose numbers have six for the second digit. Each of the other six contacts such as 127 is connected to a corresponding set of seven contacts. In the further example illustrated contact 131 is connected to conductor 630 which leads to a similar contact of relays UCR of each of the subscribers whose numbers have two for the second digit; e. g. contact 9 of relay UCR22 and contact 605 of relay UCR52.

In the present example, relay UCR56 energizes and at contact 603 completes a circuit for the pull-down winding PM of subscriber No. 56 and that magnet only as follows: battery, upper winding of relay FR, contact 109, contact 188, contact 77, contact 134, contact 135, conductor 136, contact 127, conductor 123, contact 603, pull-down winding of magnet PM56 of the line switch of subscriber No. 56 to earth. The pull-down winding of magnet PM56 accordingly energizes and causes the plunger of the subscriber's line switch to plunge closing contacts 137, 138 and 139, thereby establishing connection with the

trunk relay group TRG1. If subscriber No. 52 is free, relay UCR52 will operate and close contact 605, but no circuit will be completed for magnet PM52 since conductor 630 is only connected to the upper winding of relay FR when the units digit 2 has been registered on the chain of counting relays FR1 to FR4. The operation of the relay PM56 also opens contacts 140 and 141, thereby cutting off the line relay LR56. The circuit of relay UCR56 is opened at contact 600 but the relay remains operated for a sufficient time to allow PM56 to lock energized over its lower winding before the circuit of its upper winding is broken at contact 603. The magnet PM56 energizes over its lower winding, contact 138, release trunk conductor 143, to earth on contact 24.

It will be noted that earth is already waiting on release trunk conductor 143 so that a circuit is completed for the lower winding of relay PM56 as soon as contact 138 is closed.

If the called line were busy, no circuit would be completed for relay FR in series with the pull-down winding of relay PM56, and accordingly relay FR would not energize. It

should be understood that all the foregoing operations have taken place in between the deenergization of relay CH1 and deenergization of relay ACH1. It will be remembered that the circuit of relay ACH1 was opened

when a circuit was closed for relay TD5 at contact 112. Relay ACH1, however, owing to its slow release feature was held operated for a short time until relay FR had energized

after the plungers of idle line switches had been aligned opposite the outlet end of the trunk relay group under consideration, (trunk relay group shown in Fig. 2). If relay FR has not energized before relay ACH1 releases, the following circuit is completed:

earth, contact 73, contact 144, contact 145, contact 146, conductor 147, contact 148, conductor 46, upper winding of relay BR to battery. Relay BR accordingly energizes and gives the busy signal as previously described.

On the other hand, if subscriber No. 56 had been idle, the pull-down winding of magnet PM56 would have energized and relay FR would have energized, relay FR would open contact 146 and close a locking circuit for itself over contact 149 and contact 39 to earth

so that on relay ACH1 de-energizing relay FR would be locked up and no circuit would be completed for the busy relay. Relay

ACH1, on opening contact 60, releases the relays FR4, FR4A, FR2, FR2A, FR1, FR1A, so that all the counting relays are restored to normal. Relay ACH1 on de-energizing when relay FR is energized also completes a circuit as follows: earth, contact 73, contact

144, contact 145, contact 640, conductor 150, contact 151, switching relay SR to battery. SR accordingly energizes and is locked energized over the following circuit: battery, switching relay SR, contact 152, contact 153

130

to earth on contact 24; it closes contact 154, thereby completing a circuit for the cut-off relay COR as follows: battery, relay COR, contact 154 to earth on contact 24. It will be noted that the cut-off relay is also energized whenever relay BR energizes, due to the closure of contact 155, and the circuit completed as follows: earth, contact 24, contact 155, relay COR to battery. Relay COR, therefore, whether the called subscriber is busy or whether the calling subscriber is switched through and relay SR energized, energizes and locks itself energized over contact 156, independently of its original energizing contact, at the same time opening contact 42 so as to prevent further impulses, dialled accidentally, being transmitted to the counting relays. It also opens contact 28, thereby breaking down the holding circuit for the conductor 29, releasing relay SR1 which was locked energized at contact 157, and at the same time removing earth from the holding circuit over contact 158 and lead 37, thereby releasing the holding relay HR1. HR1 accordingly de-energizes, opens contact 38 to permit relay DR and the storage relays Y and Z to de-energize and restore to normal; at the same time it opens contact 39, thereby permitting relays SDR, SIR, and FR to de-energize. Consequently, the relay recorder group RRG1 is restored to normal condition and can be used for connecting up another call. Relay SR on energizing closed contacts 159 and 650, thereby connecting ringing current as follows: battery, source of ringing current, contact 159, conductor 160, contact 137, conductor 161, to the called subscriber's instrument set, back over conductor 162, contact 139, conductor 163, contact 650, ringing trip relay RTR to earth. The subscriber's bell, therefore, rings although relay RTR does not energize in this circuit. When, however, the called subscriber lifts his receiver, then a circuit is completed for relay RTR which energizes and opens contact 153, thereby permitting relay SR to release. Relay SR on releasing opens contacts 650 and 159 whereupon relay RTR de-energizes but without effect since the circuit of relay SR is now open at contact 152; relay SR also closes contacts 164 and 165, thereby connecting the back bridge relay BBR across the called subscriber's loop so as to feed battery thereto as follows: battery, upper winding of relay BBR, contact 164, conductor 160, contact 137, conductor 161 through the subscriber's instrument, conductor 162, contact 139, conductor 163, contact 165, lower winding of relay BBR to earth. Relay BBR on energizing closes contacts 166 and 167, thereby completing the talking circuit to the calling subscriber which can be traced by the thick lines.

It should have been mentioned that while ringing was proceeding the calling subscriber got a ringing current through the con-

denser 641, condenser 642, conductor 21, contact 17, conductor 12, subscriber's receiver, conductor 13, contact 18, conductor 22 to earth on relay LR. In case the trunk relay group in Fig. 2 should be retained in use an undue length of time, it is provided with a circuit which is completed by relay RR for the thermostat or like slow-acting device T as follows: earth, contact 168, contact 169, contact 170, thermostat to battery. The thermostat will not energize unless its circuit is closed for, say three minutes, although it would be understood that this time can be varied as desired, and it will be further noted that its circuit is opened as soon as relay SR energizes to switch the call through or BBR energizes to complete the talking circuit. It will thus be appreciated that if by any chance the trunk relay group should remain associated with the relay recorder for more than a certain allowed time, the thermostatic device will operate and connect battery to the lower winding of relay BR as follows: battery, winding of thermostat, contact 171, lower winding of relay BR, alarm relay AR to earth. Relays AR and BR accordingly energize in this circuit, AR gives an alarm to an attendant so that he can find out what is causing the delay, while the energization of relay BR serves to give a busy tone to the calling subscriber as previously described, and also to operate the cut-off relay and so disconnect the relay recorder group which is in use. It will thus be appreciated that a call has been put through to subscriber No. 56, and a connection established. To release the connection the calling subscriber hangs up and the line relay LR accordingly de-energizes, thus opening the circuit of relay RR which de-energizes and at contact 24 removes earth from the release trunk conductor 26, whereupon the cut-off relay COR and the lower winding of magnet PM56 de-energize. This causes the plunger of magnet PM56 to fall back and to release the connection to the called subscriber at contacts 137, 138 and 139, so that irrespective of whether the called subscriber has hung up or not, relay BBR will de-energize. The relays are therefore all restored to normal, the calling subscriber's line switch also restoring, when contact 24 is opened and earth removed from the release trunk 26.

It will be understood that the operation would have been similar if relay SR² had been energized in place of relay SR1, the only difference between these two relays is that relay SR1 is given preference over relay SR2. The relay group RRG2, which is not shown, is identical with the relay group RRG1.

Referring to the recorder relay group RRG1, it will be noted that a description has only been given of the effects of the transmission of sets of five and six impulses. It

will be seen that the counting relays FR1 to FR4, FR1A to FR4A are energized successively on the first four impulses, and accordingly if the first digit consists of a set of 5 1 to 4 impulses circuits are completed as follows when relay CH1 deenergizes: (we will assume the first digit is one) earth, contact 73, contact 74, contact 75, contact 76, contacts 172, 173, 58, 87, upper winding of relay W 10 to battery. Relay W locks energized in series with relay DR over contact 174 when relay ACH1 deenergizes, and closes contact 175, so that when relay SIR energizes later it completes a circuit over contact 112, contact 177, 15 contact 178, contact 179, contact 175 to conductor 180 leading to relay TD1, which is associated with the subscriber's lines, the first digit of whose number is one.

It will now be assumed that the digit 2 is 20 the first digit transmitted. The relays FR2, FR2A will lock energized, and consequently at the end of the series when relay CH1 deenergizes a circuit is completed as follows: earth, contacts 73, 74, 75, 76, 172, 181, 88, upper winding of relay X to battery. Relay X 25 accordingly energizes and locks energized over contact 182 in series with relay DR when relay ACH1 deenergizes, and closes contact 184 so that when relay SIR energizes, it completes a circuit as follows: earth, contact 112, contact 177, contact 178, contact 184, conductor 190, relay TD2 to battery.

Now assuming that the digit three had been transmitted. In this case the relays FR3 and 35 FR3A will alone be energized at the end of the series of impulses and a circuit will be completed as follows when relay CH1 deenergizes; earth, contacts 73, 74, 75, 76, 185, 89, upper winding of relay Y to battery. Relay Y 40 energizes and locks energized over contact 85 in series with relay DR when relay ACH1 releases. It opens contact 178 and closes contact 186, so that when relay SIR energizes a circuit is completed as follows: 45 earth, contacts 112, 177, 186, conductor 187, relay TD3 to battery.

If the first digit had been 4, relays FR4 and FR4A would alone be energized at the end 50 of the series of impulses and a circuit would have been completed at the end of the fourth impulse, when relay CH1 deenergized, as follows: earth, contact 73, contact 74, contact 75, contact 188, contact 189, contact 90, upper 55 winding of relay Z to battery. Relay Z energizes and locks energized over contact 82 in series with relay DR when relay ACH1 deenergizes, opens contact 177, and closes contact 113. Consequently, when relay SIR 60 energizes a circuit is completed as follows: earth, contacts 112, 113, 190, 191, 192, conductor 193, relay TD4 to battery.

A description has already been given for 65 the case in which the digit five is dialled, when relays FR4, FR4A, FR1 and FR1A re-

main energized at the end of the series of impulses.

When six impulses are transmitted relays FR4, FR4A, FR2, FR2A, FR1, FR1A are all 70 locked energized as has already been described. We will assume now that six is the first digit, in which case, when relay CH1 falls back at the end of the series of six impulses a circuit would be completed as follows: earth, contact 73, contact 74, contact 75, contact 188 contact 77, contact 134, contact 135, conductor 136, contact 91, lower winding of relay X, relay Z to battery. Relays X and Z energize in this circuit and lock energized over contacts 182 and 82 respectively in series 80 with relay DR when relay ACH1 deenergizes. Consequently when relay SIR energizes a circuit is completed at follows: earth, contact 112, contact 113, contact 190, contact 194, conductor 195, relay TD6 to battery. 85

If the first series of impulses had been seven, then when relay CH1 falls back at the end of the first series of impulses, relays FR4, FR4A, FR3, FR3A, FR2, FR2A, FR1, FR1A would all be energized and accordingly 90 a circuit would be completed as follows: earth, contacts 73, 74, 75, 188, 77, 134, 196, 92, lower winding of relay W, lower winding of relay Z to battery. Relays Z and W accordingly 95 energize in series and lock energized over contacts 174 and 82 respectively in series with relay DR when relay ACH1 deenergizes. Accordingly when relay SIR energizes it completes a circuit as follows: earth, contact 112, contact 113, contact 190, contact 191, contact 176, conductor 197, relay TD7 to battery. It is not necessary to give a description of effect of each of the units digits from 1-7 as the operation is similar irrespective of the value of the digit. 100 105

Now it is assumed that since in the arrangement proposed there will only be five talking circuits, the maximum number of subscribers will be less than fifty, as otherwise there would not be sufficient speaking 110 circuits available for simultaneous use, unless of course the traffic should be very light. Accordingly neither of the digits of the subscribers' numbers will involve the transmission of more impulses in a series than seven. 115 This it will be understood would enable 49 subscribers to be connected to the network. Generally a less number would be installed, so that the subscribers' numbers would run from 11 to 77, omitting all numbers where the 120 units figure is 8, 9 or 0. As, however, the subscriber's calling device would probably be of a standard type, capable of generating up to ten impulses, it is possible that the subscriber may make a mistake and dial the digit greater than 7, e. g. 8. When this occurs, it will be noted that when seven impulses have already been sent relays FR4 and FR3 are simultaneously energized, in fact all the 125 counting relays are energized, but this is the 130

only case where relays **FR⁴** and **FR³** are energized together, and this accordingly is sufficient for our purpose. The 8th impulse may then be traced over the following circuit: 5 earth, contacts 40, 41, 42, conductor 43, contact 51, conductor 52, contact 53, contact 68, contact 71, conductor 147, contact 148, conductor 46, upper winding of relay **BR** to battery. Relay **BR** accordingly energizes as 10 previously described and in addition to giving the busy signal cuts off the relay group **RRG1**. It will be noted that this takes place irrespective of whether the eighth impulse in a series occurs in the first or the second digit. 15 It should be understood that both the counting relay group and the storage relay group are only given by way of example, considerable modifications may be made in the arrangements so that they may deal with different numbers of digits either by increasing 20 the number of relays or by increasing the number of contacts on the relays. Such arrangements could be readily worked out by those versed in the art, having of course appreciated the spirit of the invention as disclosed in the example given.

Having given a detailed description of the setting up of a connection, it will be well to explain more particularly the operation and 25 circuit arrangements of the line and master switches and the connection of the trunk relay groups to the bank contacts thereof.

The bank contacts of calling subscribers' line switches are shown in detail in Fig. 1. 30 It will be seen that there are 10 sets of contacts, the first set having access to the inlet end of trunk relay group **TRG1**, the third set to the inlet end of trunk relay group **TRG2**, the fifth set to the inlet of trunk relay group **TRG3**, the seventh set to the inlet end of trunk relay group **TRG4**, and the ninth set to the inlet end of trunk relay group **TRG5**, while the fourth set has access to the outlet end of **TRG1** as shown, which, it 35 should be noted, is the set of contacts shown for describing the operation of the called subscriber No. 56. In fact the bank contacts of the line switch of every subscriber are connected up in the same way as those of the line switch of subscriber No. 22, but it is convenient to show only the pertinent contacts in the case of subscribers No. 22 and No. 56. The plunger arm **PA22** is considered as being in a position to close the contacts associated with inlet end of **TRG1**, but it should be understood that it can be moved under the control of the master switch to operate any one set of the ten sets of contacts.

Assuming that the plunger arms are normally in a position to operate the contacts associated with the inlet end of **TRG1**, then the wipers 606 and 103 of the master switch will be in the position shown. When a subscriber for instance No. 22, makes a call then the plunger arm **PA22** causes the contacts 17, 18, 19 and 20 to close, at contact 19 earth is connected to conductor 607, consequently a circuit is closed as follows: earth, contact 19, conductor 607, contact 23, wiper 606, contact 608, lower winding of locking magnet **LM** to battery. The locking magnet **LM** energizes and releases the master switch shaft, and closes contact 97. The master switch shaft rotates under spring and governor control carrying with it all idle 70 plungers so that they advance past bank contacts in order until the locking magnet de-energizes. At contact 97 a circuit is closed for relay **OMR** which removes earth from open main conductor **DM** at contact 100 to 75 prevent any plungers being operated while the master switch is in action. When wiper 606 reaches the next contact 609 it finds earth thereon and consequently the circuit for the locking magnet is retained and the master switch shaft continues to rotate. When wiper 606 reaches contact 610 associated with the inlet end of trunk relay group **TRG2** which it will be assumed is idle then contact 80 610 will be free from earth connections and the locking magnet **LM** will deenergize. Consequently, the master switch shaft is arrested with the plungers opposite the contacts associated with the inlet end of trunk relay group **TRG2**. If no call has originated from the time the calling subscriber No. 22 lifted his receiver until the time he completed the transmission of the wanted subscriber's number, then the position of the plunger will be 85 as described, and consequently to complete the connection of calling subscriber No. 22 with wanted subscriber No. 56 only one step of the master switch shaft is necessary, as it will be noted that wiper 103 will be resting on contact 611 when earth is received over conductor 95 due to the termination of the recording of the second digit of the wanted subscriber's number. As already described, earth on conductor 95 energizes relay **SRM** which at contact 96 completes a circuit for 90 the lower winding of the locking magnet, whereupon the master switch shaft rotates until wiper 103 reaches a contact connected to battery potential to effect the release of the master switch. As contact 105 is the contact 95 connected to battery potential it will be clear that the master switch shaft has only to move one step. After the plunger arm **PA56** has been operated and contacts 137, 138, 139 connected to conductors 160, 143, 163, associated with the outlet of trunk relay group **TRG1** the recorder is released and earth is removed from conductor 95. Relay **SRM** then deenergizes and a fresh circuit for the locking magnet **LM** is completed as follows: earth, 100 contact 612, wiper 606, contact 608, lower winding of magnet **LM** to battery. Consequently, the master switch shaft is again released and advances until wiper 606 reaches an unearthed contact which may correspond 105 to 110

to the inlet end of trunk relay group TRG3 if this group is idle.

Generally in the large majority of cases due to the comparatively small capacity of the exchange only one subscriber will be setting up a call at a time and since the trunk relay groups are taken into use in order, the succeeding trunk relay group will usually be idle and consequently the trunking arrangement shown reduces the movement of the master switch shaft to a minimum. In a similar way a call set up on trunk relay group TRG2 will, if the trunk relay group TRG3 is idle, cause the plungers to be aligned (after the call is set up) in a position to operate contacts associated with inlet end of trunk relay group TRG4; similarly in the case of calls initiated over trunk relay groups TRG3 and TRG4. In the event, however, of trunk relay group TRG5 being taken into use for instance by subscriber No. 22, then when plunger arm PA22 operates, earth is connected at contact 620 to conductor 621 which extends over wiper 606, contact 608, lower winding of locking magnet LM to battery. The locking magnet LM operates and releases the master switch shaft which rotates the wiper 606 past the earthed contact 622 to the end of its stroke. When the arm MSA operates the contacts 102 and 623, contact 102 is opened so as to prevent the locking magnet being deenergized while the wiper 103 is returning to its first position. Contact 623 closes the circuit of trip magnet TM as follows: battery, magnet TM, contact 623, contact 608, wiper 606, contact 622 earth. The trip magnet TM energizes and is mechanically locked by the detent 624. Magnet TM closes contacts 625 and 626, connecting earth at contact 626 to keep the locking magnet LM energized and at contact 625 to energize the solenoid magnet SM whereby the master switch shaft is restored to the position shown. When the master switch shaft has returned to the position shown in Fig. 1, the arm MSB forces the detent 624 out of the path of the spring controlling the armature of the trip magnet TM, which thereupon restores to normal. The contact 102 is closed and contact 623 opened by arm MSB, while the opening of contacts 625 and 626 releases the solenoid magnet SM and the locking magnet LM and if contact 23 is not connected to earth the master switch rests in this position with wiper 606 on contact 23. Otherwise the motion of the master switch shaft starts again in the forwards direction as first described.

It will be understood that if a trunk relay group were busy the master switch wipers would then always pass on to the next idle trunk relay group and this would involve, with the trunking arrangement described, the movement of the master switch shaft to the end of the forwards movement, the

master switch shaft would then be restored to its first position as described above and would then start again to find the outlet end of the required trunk relay group.

The only difference in this case would be that SRM would be energized and earth for the locking magnet LM would be maintained over contact 96. The operation of solenoid magnet SM and the trip magnet TM would be the same as before.

Referring now to drawings 14 and 15, we will assume that subscriber No. 22 initiates a call. In that case when he lifts his receiver a circuit is completed for the line relay LR22 as follows: earth, contact 14, subscriber's line 13, subscriber's instrument, conductor 12, contact 11, relay LR22 to battery. Relay LR22 energizes and closes contact 15, thereby completing a circuit as follows: earth, contact 15, pull-down coil of magnet OPM22, open main conductor, contact 700, through the resistance to battery. The magnet OPM22 energizes and causes the plunger arm OPA22 to close contacts 17, 18, 19 and 20, at the same time contacts 11 and 14 are opened, thereby breaking the circuit of relay LR22 which deenergizes shortly after. In the meanwhile, a holding circuit has been closed for the lower winding of OPM22, by earth connected to conductor 26, due to the operation of release relay of the trunk relay group, the circuit of said release relay was closed by the operation of relay LR, the circuit of this relay having been closed at contacts 17 and 18. At the same time a circuit is completed over conductor 701 to the lower winding of magnet IPM22, which however is without effect as no contact springs are controlled by IPM22 and the force exerted on the plunger arm is insufficient to cause it to operate, although the current through this winding is sufficient to hold it operated when once it has plunged. The connection of earth to contact 19 completes a circuit for the locking magnet OLM as follows: earth, contact 19, conductor 704, wiper 703, magnet OLM to battery. Magnet OLM energizes and closes contact 702, thereby completing a circuit for relay OOM, which energizes and opens contact 700, thereby removing battery from the open main conductor and thus preventing the operation of any other line switches, such as OLS22, at this time. Magnet OLM also releases the master switch shaft so that the wiper 703 passes to the next contact and if this contact is idle the circuit of OLM is opened so that this relay deenergizes and locks the master switch shaft with the plungers opposite the inlet end of the next trunk relay group corresponding to Fig. 2. If this trunk were busy, earth would be found on contact 705 and the wiper 703 would advance to the next step and so on, until an idle trunk relay group was found. If the wiper 703 had been initially resting

upon the eighth or ninth contacts and the subsequent contacts had all been busy, or it had been resting on the tenth contact, then a circuit would have been completed for trip magnet OTM as follows: battery, relay OTM, contact 706 to earth on wiper 703. OTM on energizing will complete a circuit for itself at contact 707 independent of wiper 703 and at contact 708 will have completed a circuit for the solenoid magnet OSM which accordingly energizes and restores the plungers and the wiper 703 to the position shown. Relay OLM has also been energized at this time and when the wipers are all restored to the position shown, contact 706 is opened, magnet OTM releases, and relay OLM is energized, or not, according as to whether the wiper 703 is resting on an earthed contact. Relay OOM is energized continuously during the movement of the plungers, so that battery is removed from conductor OM throughout this period, and for a short time after, so that no line switch can plunge during the operation of the master switch. The wiper 703, if now resting on a busy contact continues to hunt as before until an idle line is found.

The further operation of setting up a connection proceeds as previously described with relation to Figs. 2, 4 and 5, and when the called number, which we assume is 56, is called, the following operations take place assuming that subscriber No. 56 is idle. In that case, a circuit will be completed as follows when relay CH1 deenergizes and relay ACH1 is still energized: earth, contact 73, contact 74, contact 86, relay SDR to battery. Relay SDR on energizing connects relay SIR over contact 108, conductor 107, contact 106, conductor 104 to contact 709 in the bank of contacts of the master switch IMS, which are wiped over by wiper 710. At the same time earth is connected to conductor 95 at contact 94, thereby completing a circuit for relay ISR. Relay ISR energizes and at contact 711 connects earth to energize the upper winding of the locking magnet ILM. ILM energizes and permits the plungers and the master switch wiper to advance one step. In this position battery is found on contact 709 through the winding of relay SIR, consequently the two windings of the magnet ILM are energized in opposition and magnet ILM releases, while at the same time relay SIR energizes.

It will be noted that the circuit of the lower neutralizing winding of magnet ILM passes over contact 712 of relay ISR and also over contact 713. This is to insure that the locking magnet cannot be released when the solenoid magnet ISM is energized and the plungers are being restored to the starting position as shown in Fig. 15 with the wiper 710 on the extreme right-hand contact. When relay SIR energizes a circuit is com-

pleted for the upper winding of relay FR as follows: battery, upper winding of relay FR, contact 109, contact 188, contact 77, contact 134, contact 135, conductor 136, contact 127 of relay UR, Fig. 5, conductor 133, upper winding of magnet IPM56, conductor 723, contact 715, of the line switch OLS56, conductor 123, contact 121 of relay TD5 to earth. Consequently in this circuit relay FR and the magnet IPM56 energizes. The magnet IPM56 now receives sufficient current to cause the plunger arm to plunge and close contacts 724, 725, and 726, so that conductors 160 and 163 are connected to conductors 161 and 162 respectively and thence to the instrument of subscriber No. 56; at the same time earth is connected over contact 725 in the following circuit: earth on contact 24, conductor 143, contact 725 to the lower windings of magnets IPM56 and OPM56. This serves to maintain the plunger of line switch ILS56 operated, while at the same time magnet OPM56 energizes and opens contacts 715, 727 and 728. At contacts 727 and 728 it disconnects the line relay LR56 from across the conductors 161 and 162 and so prevents the plunger of line switch OLS56 being operated when the called subscriber lifts his receiver. At contact 715 it opens the circuit of the pull-down coil, i. e., the upper winding of magnet IPM56 and so prevents any circuit being completed for a relay such as FR of another recorder or of the same recorder, if it had been set up by another subscriber to establish a connection with subscriber No. 56, while subscriber No. 56 was still engaged with the calling subscriber No. 22.

It will be noted, therefore, that if subscriber No. 56 had been engaged prior to his being called by subscriber No. 22 on either an incoming or outgoing call, contact 715 would be opened and consequently no circuit would be completed for relay FR, the result being that busy relay BR would be operated as previously described, when the relay ACH1 finally permitted its armature to fall back.

It will thus be appreciated that by the arrangement described approximately same results are achieved as in the case of the former arrangement, except that in this case it is possible to have up to ten speaking circuits. It will be noted that the lead 104 associated with the trunk relay group shown in Fig. 2, is connected to the second contact in the bank of wiper 710, while the lead 704 is associated with the first contact in the bank wiped over by wiper 703. The connections are shown in this way for convenience so that the operation of IMS can be described without the wiper 710 initially resting on the contact selected, but probably the best arrangement is that conductor 104 should be connected to the first contact in a similar manner to conductor 704, and further that

all the conductors should be connected up in the same order, that is, the inlet ends should be connected in the same order as the outlet ends. In the case where the wiper 710 is 5 normally resting in a position beyond the contact for which it is hunting, then the wiper 710 will advance to the tenth contact position, whereupon contact 713 is opened and contact 730 is closed; a circuit is thereby completed 10 for the trip magnet ITM as follows: battery, magnet ITM, contact 730, contact 711 to earth, relay ISR being of course energized when a hunting operation is in progress. Magnet ITM energizes and closes a locking 15 circuit for itself at contact 731 and at contact 732 completes a circuit for the solenoid ISM, which thereupon energizes and moves all the plungers back to the position shown. When this position is reached contact 730 is 20 opened and contact 713 closed, thereby enabling the locking magnet ILM to be neutralized by battery over wiper 710, the springs of magnet ITM are also released, thus opening the locking circuit of ITM so as to permit 25 this magnet to restore to normal and the solenoid ISM to deenergize.

Fig. 6 shows a general layout and Figs. 7, 8, 9, 10, 11, 12 and 13 show detailed circuits of an alternative arrangement, using in place 30 of the plunger type line switch, line switches which are adapted to wipe over contacts and rotate in a single level. For this purpose the line switch bank is divided into two parts so that when a subscriber calls, his line switch 35 operates to select an idle line in the first part, which we will call "A." This gives him access to a trunk relay group TRG which in turn on seizure causes a recorder R to be connected up to it by means of a recorder finder 40 RF. The subscriber then operates his impulse sender to send a series of impulses depending in number upon the call he requires. If he requires a call to the main exchange he dials the digit 0, thus sending ten impulses, 45 whereupon a circuit is completed which causes the main trunk relay group MTRG to operate and the wipers of the switch associated therewith to rotate and establish connection with the trunk relay group TRG which is in use. On such connection being 50 established the trunk relay group TRG is disconnected and the recorder is restored to normal so that it can be used for another call. The subscriber then operates his impulse sender to send a series of impulses corresponding to the number of the subscriber 55 he requires in the main exchange.

If, on the other hand, the subscriber desires connection with another local subscriber he operates the recorder for two digits and on the transmission of the second digit, if the called subscriber's line is free, he causes the line switch of that subscriber to hunt in the part "B" of its bank to find the 60 outlet end of the trunk relay group, of which

the inlet end has been taken into use by the calling subscriber, whereupon a connection is completed between the two local subscribers as will be understood more directly from study of the individual circuits. Another 70 alternative which might happen is that a main exchange subscriber may desire to talk with a subscriber in the sub-exchange, in which case, when a relay in the main trunk relay group MTRG is seized, the line switch 75 associated therewith will hunt. Not, however, in the first part of its bank, which may be referred to as the "C" part, but in the second part of its bank which may be referred to as the "D" part. The only difference between the "C" and "D" parts is that a different test wiper is used, the test wiper in this case hunting to find an idle trunk relay group and not, as before, a trunk relay group which had already received, according 80 to the recorder associated therewith, a series of ten impulses. The recorder is seized in exactly the same way as if the call had initiated from a calling subscriber, and the impulses from the main exchange are 85 also received and recorded and the called subscriber's line switch (if it is free) operated to connect with the "B" part of its bank so that the connection will be completed as follows: over the trunk line, through the "D" 90 part of the line switch bank associated with the main trunk relay group MTRG, through a trunk relay group TRG, through the "B" part of the line switch bank of the called subscriber to the called subscriber's instrument. 100

Reference should now be had to Figs. 7, 8, 9, 10, 11, 12, and 13 for a complete disclosure of the operating circuits. We will assume in the first place that a local subscriber 105 No. 22 wishes to establish connection with another local subscriber whose number we will assume to be 56. He accordingly lifts his receiver preparatory to setting up the call and thereupon completes a circuit as follows: 110 battery, line relay LR22, contact 200, contact 201, conductor 202, through the subscriber's instrument back over conductor 203, contact 204 to earth. LR22 accordingly energizes 115 and closes contacts 205 and 206, at the same time opening contact 207 thereby removing earth from the lower winding of the change relay CR22 so as to signify that this line is busy in case a call should be extended to the calling subscriber's line switch. 120

Contact 205 closes a circuit as follows: battery, magnet M22, interrupter contact 208, contact 205, contact 209, contact 210, wiper P22, so that if the wiper P22 is resting on an earthed contact the magnet M22 will operate 125 and step the switch until an unearthed contact is reached. LR22 in closing contact 206 completed a circuit as follows: earth, contact 206, contact 211, cut-off relay COR22, contact 208, magnet M22 to battery. The relay 130

COR22 is short-circuited, however, as long as wiper P22 rests on an earthed contact. As soon as an unearthing contact is reached, which it will be assumed corresponds to the 5 trunk relay group TRG, then relay COR22 will energize. In doing so, it opens contacts 200 and 204, and closes contacts 212 and 213, thereby completing a circuit for the line relay LRT of the trunk relay group TRG as follows: battery, upper winding of relay LRT, conductor 214, contact 215, conductor 221, contact 217, wiper 218, contact 212, conductor 202, through the subscriber's instrument, back over conductor 203, contact 213, 10 wiper 219, contact 220, conductor 222, contact 223, conductor 224, lower winding of relay LRT to earth. Relay LRT accordingly energizes and closes contact 225, thereby completing a circuit for release relay RRT. 15 Relay RRT energizes and closes contact 226, thereby connecting earth to the release trunk conductor 227 which extends over contact 228, conductor 229, test contact 230, wiper P22, contact 210, contact 231, contact 211, relay COR22, contact 208, magnet M22 to battery. This accordingly serves to hold relay COR22 energized after contact 206 has been opened, owing to relay COR22, on energization, having opened 20 the circuit of relay LR22 at contacts 200 and 204. Relay COR22 also opens contact 232, thereby maintaining open the circuit of the lower winding of relay CR22 after contact 207 has closed, which it does shortly after. 25 The relay LRT also opens contact 233 and closes contact 234, which has no effect at this time. Release relay RRT on energizing, in addition to closing contact 226, opens contact 235 and closes contact 236. It also closes contacts 247 and 238. The closure of contact 238 completes a circuit as follows: earth, contact 238, contact 239, conductor 240, contact 241 (Fig. 9), contact 242, finder start relay FSR to battery. It is being assumed that 30 the recorder shown in Fig. 9 is idle.

If it had been busy, the circuit, instead of extending to relay FSR, would have extended over contact 243 instead of over contact 241, contact 246 to conductor 245; contact 246 is controlled by relay FSR, and simply serves to prevent two relays such as FSR being energized simultaneously, and extends to a conductor similar to conductor 240 for other recorders. Generally in an exchange of the 35 size contemplated two recorders are sufficient. If there had been a third recorder, however, a similar circuit would have simply extended to a third conductor similar to conductors 240 and 245 and according as to whether the 40 first, second or third recorder is idle, the relay FSR associated therewith would have been operated, and further operations would have taken place in the manner hereinafter to be described.

It may be assumed, however, for the mo-

ment that there are no recorders available, in which case when the calling subscriber commences to dial and the line relay LRT de-energizes at the first impulse a circuit is completed as follows: earth, contact 226, contact 233, contact 247, contact 248, contact 323, busy relay BRT to battery. Relay BRT accordingly energizes and locks itself energized at contact 249 in series with earth on contact 226; it opens contact 250 and closes contact 251 thereby connecting busy tone through condenser 252 to the conductor 214 and thence over the previously described circuit to conductor 202 and to the subscriber's instrument, thereby informing him that he cannot obtain 70 connection with the subscriber he requires. He thereupon will hang up his receiver allowing line relay LRT to de-energize, which will be followed shortly after by the release relay RRT, whereupon contact 226 will be 75 opened thus allowing relay COR22 to de-energize and the line switch LS22 will be restored to normal. Similarly relay BRT in the trunk relay group TRG will de-energize on the opening of contact 226.

If, however, the recorder shown in Fig. 9 is free, relay FSR will energize and the subsequent operation will now be described. Relay FSR opens contact 246 and closes contacts 253 and 254, thereby completing a circuit as follows: battery, magnet MF, inter- 90 rupter contact 255, contact 254, contact 256, test wiper 257, test contact 258, conductor 259, on which earth will be resting if the trunk relay group on which the wipers of the recorder finder RF is not in a condition corresponding to the initiation of the call. For instance, if the trunk relay group TRG were idle, earth would be found over contacts 260 and 235. If, however, a trunk relay group 95 has taken a recorder into use, earth would be found over contacts similar to contacts 236, 654, 652, and 226, since it will be seen that relay FTR is energized by earth over contact 253 and conductor 259 as soon as the trunk relay group TRG is seized by the finder RF. It is clear therefore that magnet MF will operate intermittently until the recorder finder RF finds a trunk relay group, such as TRG, in which the test contact is not earthed.

It will now be assumed that the trunk relay group TRG is idle, in which case a circuit may be traced as follows: earth, contact 253, relay FCR, contact 254, contact 256, test wiper 257, test contact 258, conductor 259, 100 contact 236, contact 261, relay FTR to battery. Relays FTR and FCR accordingly energized in series over this circuit and relay FTR completes a locking circuit for itself over contact 652 to earth on contact 226 and 105 also places earth on the test contact 258 over the following circuit: earth, contact 226, contact 652, contact 654, contact 236, conductor 259, test contact 258, thereby marking the 110 trunk relay group TRG busy to recorder 130

finders. Relay FCR completes a locking circuit for itself as follows: earth on contact 226, contact 652, contact 654, contact 236, conductor 259, test contact 258, test wiper 257, contact 262, relay FCR, interrupter contact 255, magnet MF to battery. Magnet MF does not operate over this circuit owing to the resistance of relay FCR. Relay FCR also closes contact 263, thereby energizing the auxiliary relay AFCR. It should be noted that relay FCR opens contact 242 and closes contact 244, thereby preparing a circuit between conductors 240 and 245 over contacts 241 and 244, so that another finder can be started as soon as relay FSR deenergizes, upon the opening of its circuit at contact 242. Earth, however, was removed from finder-start conductor 240, by the opening of contact 239 when relay FTR operated.

20 The subscriber now commences to dial the first series of impulses, which, since he is calling subscriber No. 56, will consist of five impulses. On the first deenergization of relay LRT a circuit is completed as follows: 25 earth, contact 226, contact 233, contact 247, contact 264, conductor 265, contact 266, wiper 267, contact 268, wiper 271 and normal contact 269 of tens recording switch TRS, low resistance relay TLRR, magnet TM to battery. The magnet TM and the low resistance relay TLRR accordingly respond to the first impulse of the series. Relay TLRR is slow to release so that it remains energized throughout the train of impulses, and 30 at contact 270 closes a circuit for subsequent impulses of the series as follows: over wiper 271, any of the contacts engaged by said wiper when in an off-normal position, contact 270, relay TLRR, magnet TM to battery, this circuit being independent of the normal contact 269. Consequently the wipers 271, 272 and 273 are stepped to the fifth off-normal position, in which position they remain at the end of the series of 45 impulses. At the end of the series of impulses relay TLRR deenergizes and a new impulsive circuit is prepared for the next series of impulses.

50 The subscriber now operates his calling device to transmit the second series of impulses, which in this case would consist of six, and the first impulse of this series may be traced as follows: earth, contact 226, contact 233, contact 247, contact 264, conductor 265, bank contact 266, wiper 267, contact 268, wiper 271 at the fifth off-normal position, the contact engaged thereby, contact 274, low resistance relay ULR, normal contact 275 of units recording switch URS, wiper 276, magnet UM to battery. The magnet UM accordingly responds to the first impulse and advances the wipers 276, 277 and 278 one step. Relay ULR which is energized on the first impulse remains energized through 60 the train of impulses as it is slow to release.

On energizing on the first impulse it closes contact 279, so that subsequent impulses pass over the following circuit; earth, contact 226, contact 283, contact 247, contact 264, conductor 265, bank contact 266, wiper 267, contact 268, wiper 271, the sixth bank contact on which this wiper is resting, contact 274, relay ULR, contact 279, any of the off-normal contacts on which wiper 276 may be resting, wiper 276, magnet UM to battery. Accordingly magnet UM steps the wipers 276, 277 and 278 to the seventh position and relay ULR deenergizes at the end of the series of impulses thereby closing contact 280.

A circuit is now completed as follows: earth, wiper 277, seventh contact on which said wiper is resting, conductor 281, contact 282, contact 280, contact 283, relay MSR1 to battery. It should be noted that contact 283 is on relay MSR2 corresponding to the relay MSR1, but associated with the other recorder, assuming that there are only two recorders. If there are more, an arrangement could be readily worked out in which only one relay MSR1 would be operated at a time. It will be noted that the relay MSR1 on energizing opens contact 284 to prevent relay MSR2 from energizing. It will be assumed that relay MSR2, however, is not energized at this time, otherwise a pause would ensue until relay MSR2 released. Relay MSR1 on energizing, in addition to opening contact 284, closes contacts 285, 286, 287, 288. Contact 288 completes a circuit for slow acting relay SAR, but this relay does not operate until there has been time for a further set of operations to take place, these operations will now be described.

It should be noted that a branch circuit is completed for impulsive cut-off relay ICO as follows: earth, wiper 277, seventh bank contact, conductor 281, contact 282, contact 280, relay ICO to battery. Relay ICO energizes and opens contact 268, thereby breaking the impulsive circuit so that no further impulse can influence the recorder. Relay ICO also closes contact 289, thereby completing a circuit as follows: earth, contact 286 of relay MSR1, contact 289 wiper 267, bank contact 266, conductor 265, contact 264, contact 247, contact 234, relay LRT being energized after the impulse train, contact 250, relay MPR to battery. Relay MPR energizes and closes contacts 290 and 291 and opens contacts 292. By opening contact 292 it removes earth from the outgoing test contact 293 Fig. 7, as it will be noted that earth is normally connected to test contact 293 as follows: earth, contact 292, contact 294, conductor 295, to test contact 293, while at contact 291 it connects the called line test relay CTR to test contact 293. The closure of contact 285 by relay MSR1 completes a circuit as follows: battery through the resistance, contact 285, wiper 273, the sixth con-

tact 296 on which wiper 273 is resting, conductor 297, lower winding of relay CR56, contact 298, contact 299 to earth. This circuit, as will be noted, is dependent upon the called line being idle, and is open if either line relay LR56 or cut-off relay COR56 are energized.

It will be assumed in the first case that the line is idle and that the foregoing circuit is completed as described. Consequently relay CR56 will energize in this circuit and open contact 300, thereby disconnecting the line relay LR56 from across conductors 301 and 302 of the subscriber's line. Relay CR56 also closes contacts 303, 304 and 307 thereby completing a circuit for itself at contact 304, which is independent of contact 299, and removes the short circuit across its upper winding at contact 305. A circuit will now be completed over contact 303 as follows: earth, relay UTR, contact 287, wiper 278, the seventh contact 308 on which this wiper is resting, conductor 309, contact 303, contact 310, relay LR56 to battery. Relays LR56 and UTR accordingly energize; relay UTR opens contact 311 so that when relay SAR energizes and closes contact 312, no circuit can be completed. Relay LR56 on energizing opens contact 299 and closes contact 313; it also closes contact 314. A circuit is therefore completed for the magnet M56 as follows: battery, magnet M56, interrupter contact 315, contact 314, contact 316, contact 307, test wiper Q56, which wiper will usually be resting on an earthed contact.

This is because the contacts on which wiper Q56 are resting are connected to earth directly for the positions corresponding to the inlet end of a trunk relay group such as TRG, whilst the contacts corresponding to the outlet end of a trunk relay group are all connected to earth over contacts of relays such as CTR and MPR, except a calling trunk relay group as described; in fact the only test contact which is disconnected from earth at this time will be contact 293. This is because a relay such as MPR can only be energized in a trunk relay group which is associated with a recorder having its relay MSR1 energized, and only one relay such as MSR1, in the various recorders, can be energized at a time. Consequently the magnet M56 energizes and rotates the wipers 317, 318, P56, and Q56 until the wiper Q56 rests on contact 293. When this happens the magnet M56 ceases to operate and a circuit is completed as follows: earth, contact 313, upper winding of relay CR56, relay COR56, contact 315, magnet M56 to battery. Relay COR56 energizes in series with the upper winding of relay CR56 in this circuit and opens contact 310, thereby disconnecting the line relay LR56, and the relay UTR this relay however is made slow to release so that before it falls back to close contact 311, relay CTR has energized and opened the cir-

cuit of the busy relay BRT. Relay COR56 closes contacts 329 and 330 thereby connecting the subscribers loop to the outlet end of the trunk relay group TRG in readiness for the transmission of ringing current. Relay COR56 also opens contacts 316 and 298. The opening of contact 316 prevents any further operation of the magnet M56, and the opening of contact 298 opens the circuit of the lower winding of relay CR56, but relay CR56 remains energized over its upper winding in series with relay COR56 from earth on contact 313. Before relay LR56 falls back a circuit is completed for relay CTR as follows: earth, contact 313, contact 320, contact 307, wiper Q56, contact 293, conductor 295, contact 291, relay CTR to battery. Relay CTR energizes and at contact 319 closes a locking circuit for relays CR56 and COR56 in series as follows: battery, magnet M56, contact 315, relay COR56, upper winding of relay CR56, contact 320, contact 307, wiper Q56, contact 293, conductor 295, contact 291, contact 319, to earth on contact 226. Relay CTR on energizing in addition to completing a locking circuit for relays CR56 and COR56 at contact 319 as previously described, also opens contacts 294 and 323 and closes contacts 321, 322 and 653. It will be noted that the effect of closing contact 319 is to maintain earth potential over either contact 291 or contact 321 to conductor 295, so that test wiper 293 is maintained in connection with earth potential so as to render the outlet end of the trunk relay group TRG inaccessible to any other called subscriber.

At contact 322 relay CTR closes a circuit for the ringing relay SRT as follows: earth, contact 226, contact 322, contact 290, relay SRT to battery. Relay SRT energizes, and completes a locking circuit for itself as follows: earth, contact 226, contact 335, contact 333, relay SRT to battery, and at contacts 325 and 326 completes a circuit for ringing current as follows: ringing generator through contact 325, conductor 327, contact 328, wiper 317, contact 329, conductor 301 through the bell and condenser of subscriber's instrument, back over conductor 302, contact 330, wiper 318, contact 331, conductor 324, contact 326, resistance 336 to earth. At contact 656 the upper winding of relay BBR is short-circuited and at contact 326 the lower winding of relay BBR is shunted by a resistance, the relay is thus made slow and will not energize on alternating current. The subscriber's bell is accordingly rung intermittently as in the well-known manner. Relay CTR opens contact 323 in order to prevent a circuit being closed for relay BRT when relay FTR or relay UTR falls back.

At contact 653 a circuit is closed for the recorder release relay RRR which energizes and opens contacts 261 and 654. Earth is mo-

mentarily removed from conductor 259 by the opening of contact 654 thus opening the locking circuit of relay FCR which deenergizes. At contact 263 relay FCR opens the circuit of relay AFCR which falls back and closes contacts 344 and 345 whereupon a circuit is completed as follows: earth, wiper 277, which is resting on the seventh contact, conductor 281, contact 343, upper winding of off-normal relay ONR, interrupter contact 344, magnet UM to battery. This causes the magnet UM to step wipers 276, 277 and 278 round to normal. Another circuit is completed as follows: earth, wiper 272, contacts 346, lower winding of relay ONR, interrupter contact 347, magnet TM to battery. Magnet TM steps automatically in this circuit to bring the wipers round to the eleventh contact. At the eleventh contact a circuit is completed as follows: earth, wiper 272, eleventh contact 348, contact 346, lower winding of relay ONR, interrupter contact 347, magnet TM. The magnet TM accordingly makes another step to step the wipers 271, 272 and 273 to their normal position. It should be understood that the switches TRS and URS are of the type in which the wipers move in a continuously forward direction, and they have eleven contacts, one normal and ten off-normal contacts. The wipers have two arms diametrically opposite and the contacts are arranged in a semi-circle so that when one arm of the wiper arm comes off the last contact, the opposite end of the wiper arm simultaneously engages the first contact. Relay ONR is energized to keep contact 243 closed as long as the magnets are restoring the wipers to normal. As soon as the wipers have restored to normal, relay ONR deenergizes and closes contact 241. The purpose of closing contact 243 it will be noted is to maintain conductor 240 connected to conductor 245 until the recorder is in a position to restore to normal; relay FSR is made slow to pull up to avoid any possibility of its operating due to a momentary closing of its circuit. It will be noted that the relays ICO and MSR1 restore to normal when contact 282 is opened, and that relay MSR1 opens the circuit of relay SAR at contact 288, and the circuit of relay MPR at contact 286. Relay FTR falls back a short time after the energization of relay RRR and replaces earth on test contact 258 over the following circuit: earth, contact 226, contact 651, contact 655, contact 236, conductor 259, test contact 258, thereby marking the trunk relay group TRG busy to the recorder finders.

A branch circuit of the ringing current through resistance 336 extends over conductor 337, the lower winding of back bridge relay BBR to earth. The back bridge relay does not energize on ringing current but since the generator is fed back in series with battery a direct current circuit is completed when the calling subscriber lifts his receiver, so

that relay BBR is enabled to energize over its lower winding as follows: earth, lower winding of relay BBR, conductor 324, contact 331, wiper 318, contact 330, subscriber's loop, contact 329, wiper 317, contact 328, conductor 327, contact 325 to battery. At contact 335 relay BBR opens the circuit of relay SRT which releases and by closing contacts 338 and opening contacts 656 and 326 completes a circuit for relay BBR over both its windings as follows: earth, lower winding of relay BBR, conductor 337, conductor 324, contact 331, wiper 318, contact 330, conductor 302, through subscriber's instrument, conductor 301, contact 329, wiper 317, contact 328, conductor 327, contact 338, conductor 339, upper winding of relay BBR to battery. Relay BBR accordingly is maintained energized as long as the called subscriber's receiver is off the hook. Relay BBR closes contact 340 to complete the speaking circuit and contact 341 to short-circuit the condenser 242 which had served to bring the ring-back of ringing circuit to the calling line. The speaking circuit may then be traced in thick lines from the calling subscriber to the called subscriber.

When the subscribers have finished their conversation the calling subscriber restores his receiver and relay LRT deenergizes. This is followed by relay RRT which opens contact 226, thereby removing earth from the release trunk conductor and permitting the relays CR56 and COR56 of the called subscriber's line switch to deenergize and restore the called subscriber's line switch to normal condition, and permitting relay COR22 of the calling subscriber's line switch to deenergize and restore the calling subscriber's switch to normal condition. The removal of earth from the release trunk conductor allows the relay CTR to deenergize, at contact 653 relay CTR opens the circuit of relay RRR which accordingly deenergizes and the circuit of the trunk relay group is restored to normal.

A description will now be given, assuming that the called subscriber was busy. In such a case the relay UTR would not energize, as in the first place there would be no circuit for relay CR56 due to contact 310 being open. Consequently relay SAR would have energized before relay UTR and a circuit would have been completed as follows: earth, contact 312, contact 311, wiper 349, contact 350, conductor 351, contact 323, relay BRT to battery. Relay BRT will energize, lock itself energized at contact 249, open contact 250 and close contact 251, connecting busy tone to the calling subscriber. The relay BRT also closes contact 662 thereby closing a circuit for the relay RRR which energizes to release the recorder in the manner already described.

Having described how a subscriber at the private exchange can obtain access to another subscriber at the private exchange, a

description will now be given of how a subscriber at a sub-exchange can obtain access to a main exchange subscriber. In this case the connection is exactly the same as previously described, except that when he dials the first digit, instead of dialling five, he dials ten and therefore steps wipers 271, 272 and 273 to the eleventh contact, in which case wiper 272 rests on contact 348. Thereupon a circuit is completed as follows: earth, wiper 272, contact 343, contact 350, contact 280, contact 283, relay MSR1 to battery. Relay MSR1 accordingly energizes (assuming that no other recorder is marking at this time) and closes contacts 285, 286, 287, and 288 as before. The following circuits are then completed: battery, contact 285, wiper 273, contact 352, wiper 353, contact 354, conductor 355, relay MTR to earth. Relay MTR accordingly operates, closes contact 356, thereby connecting earth to conductor 229, independently of the earth over contacts 228 and 226; and opens contact 357, thereby disconnecting earth from conductor 227. Relay MTR also closes contact 359 to connect the switching over relay SOR to test contact 358 over conductor 227. Simultaneously with the operation of relay MTR and removal of earth from the contact 357, a circuit is completed as follows: earth, relay UTR, contact 287, wiper 278 in normal position, normal contact 360, conductor 361, contact 362 (Fig. 10), contact 363, upper winding of relay LRM to battery. Relay LRM energizes in this circuit and closes a circuit for relay RRM at contact 364. Relay RRM energizes and closes contacts 365 and 366; at contact 366 a circuit is completed as follows: test wiper 367, contact 368, contact 366, interrupter contact 369, magnet MM to battery.

Magnet MM operates intermittently therefore, as long as the wiper 367 is resting on an earthed contact, which occurs until the contact 358 of trunk relay group TRG is reached as all other contacts similar to contact 358 have earth connected thereto either over contacts such as 370 and 357, if the trunk relay group with which they are associated is idle or is engaged on a local connection, or over contacts such as 365 and 374 if the trunk relay group has been seized by a main trunk relay group such as MTRG. When contact 358 is reached, however, due to it being in a special condition determined by relay MTR being operated, the circuit for a switching through relay STM becomes effective as follows: earth, contact 365, relay STM, contact 369, magnet MM to battery. Relay STM which is of high resistance, alone energizes in this circuit, and opens contacts 363 and 368 and closes contacts 372, 373 and 374. The closure of contact 374 completes a circuit as follows: earth, contact 365, contact 374, wiper 367, contact 358, conductor 227, contact 359, relay SOR to battery. Relay SOR energizes opens contacts 215, 228 and 223, thus disconnecting conductors 221, 229 and 222 from conductors 214, 227 and 224 respectively, and thereby effectively isolating and releasing the trunk relay group TRG, which accordingly restores to normal as previously described and releases the associated recorder. Relay SOR completes a locking circuit for itself over contact 644, conductor 227, contact 358, wiper 367, contact 374, contact 365, to earth. Relay SOR also opens contact 370, thereby preventing earth being connected over contact 357 to test contact 358, when relay MTR releases, which it does immediately the recorder is released.

A circuit is now completed for relay LRM independent of its original energizing circuit as follows: battery, upper winding of relay LRM, contact 372, wiper 376, contact 377, conductor 221, contact 217, wiper 218, contact 212, conductor 202, calling subscriber's loop, conductor 203, contact 213, wiper 219, test contact 220, conductor 222, contact 378, wiper 379, contact 373, lower winding of relay LRM to earth. Relay LRM is therefore maintained energized and maintains the circuit of relay RRM, which in turn maintains the circuit of relay STM. Relay RRM on energizing completed a circuit for outlet relay ORM as follows: earth, contact 380, relay ORM to battery. Relay ORM energizes to disconnect the dry relay DRM from across the conductors 381 and 382, at contacts 383 and 384 respectively and at the same time closes contacts 385 and 386 to complete a circuit over the trunk line which may be traced as follows: battery, upper winding of retard coil RCM, contact 387, contact 385, conductor 381 through a dry relay DRE at the exchange, back over conductor 382, contact 386, lower winding of retard coil RCM to earth. The dry relay DRE, that is, the relay at the main exchange without battery or earth connections is thereby energized and prepared for the reception of impulses, a description of which will be given later.

Everything is now in readiness for the transmission of impulses to the main exchange, and consequently the calling subscriber now operates his impulse sender to transmit a series of impulses corresponding to the first digit of the number of the main exchange subscriber. As far as the operation at the sub-exchange is concerned each series of impulses produced the same effect and it will be sufficient for our purpose if we describe only one series of impulses. When relay LRM deenergizes on the first impulse it opens contact 387, thereby opening the loop circuit over conductors 381 and 382 and permitting the relay DRE at the exchange to deenergize. At the same time it closes contact 388, thereby completing a circuit for change relay CHM as follows: earth, contact 388, contact 389, relay CHM to bat-

tery. Relay CHM energizes and closes contacts 390 and 391; at contact 391 it short-circuits the lower winding of the retard coil RCM and at contact 390 it connects a resistance in shunt with the upper winding of the retard coil RCM. The effect of this is to increase the efficiency of the impulsive circuit. It will be appreciated that the further series of impulses do not materially differ as regards operation at the sub-exchange from the operations effected by the first series of impulses so that the only operations that need be further considered at this time are the completion of the talking circuit and the release.

The talking circuit is completed from the main exchange over conductor 381, contact 385, contact 387, contact 392, condenser 393, contact 372, wiper 376, contact 377, conductor 221, thence over the previously described circuit of the calling subscriber's loop back over conductor 222, contact 378, wiper 379, contact 373, condenser 394, contact 386, to conductor 382, battery being fed to the calling subscriber by relay LRM and to the called subscriber by battery at the main exchange. If a busy signal is received its circuit may be traced in a similar way over the talking circuit, while when the subscribers hang up their receivers at the end of the conversation the calling subscriber causes the release of relay LRM, which permits relay RRM to deenergize, which in turn permits the release of relays ORM and STM, thereby restoring the main trunk relay group MTRG to normal.

The removal of earth from conductor 227 by the opening of contact 365 permits relay SOR and also the cut-off relay COR22 to deenergize. COR22 upon deenergizing restores the line switch to normal so that everything is now in readiness for use on another call.

A description will now be given of the operations which take place when the calling subscriber is in the main exchange and desires to set up connection with a subscriber in the sub-exchange. Without going, at this juncture, into a description of the operation at the main exchange, which will be described later, it is sufficient to say that when the subscriber at the main exchange establishes connection with a trunk line such as conductors 381 and 382, battery is fed forward to energize the relay DRM over the following circuit: battery on conductor 381, contact 383, winding of relay DRM, contact 384, conductor 382 to earth at the main exchange. Relay DRM accordingly energizes and closes contact 395, thereby closing a circuit for release relay RMT. Relay RMT energizes and closes contacts 411, 396 and 397. At contact 397 it completes a circuit as follows: earth on a test contact such as 403 (assuming that the trunk relay group associated therewith is busy), test wiper 398, conductor 399, contact 400, contact 397, interrupter contact 369,

magnet MM to battery. The operation therefore is dependent upon whether wiper 398 is resting on an earthed contact. It should be mentioned that the wiper 398 has access to contacts such as 403 which are multiplied to contacts such as contacts 230. The magnet, therefore, operates until an unearthing contact is reached, which it will be assumed is contact 403, which is connected to lead 229 and therefore multiplied to contact 230, indicating that the trunk relay group TRG is free.

When this occurs a circuit becomes effective for the relay COM as follows: earth, contact 396, relay COM, interrupter contact 369, magnet MM to battery. COM is of high resistance and therefore alone energizes in this circuit and opens contact 400 and closes contacts 404, 405, and 406. At contact 406 it connects earth to conductor 399 so as to mark the test contact 403 and test contacts such as 230 busy. At contacts 404 and 405 it completes a circuit across the line wipers 376 and 379 as follows: wiper 376, conductor 407, contact 405, contact 408, winding of retard coil RTC, contact 404, conductor 409, wiper 379. This is equivalent, in every respect as regards the trunk relay group TRG, to a connection by a calling subscriber's line switch, and it will be noted that contacts 377 and 378 are permanently multiplied to contacts such as 217 and 220 respectively. When impulses come in from the main exchange the relay DRM responds thereto and opens contact 408; at the same time it closes contact 410, thereby completing a circuit as follows: earth, contact 410, contact 411, relay IIR to battery. Relay IIR energizes and closes contact 412, thereby short-circuiting the retard RTC to improve the impulsive. The main exchange subscriber now dials two digits corresponding to the number of a subscriber in the local exchange, and this operation need not be described as it is identical with the description given of called subscriber No. 22 connecting to calling subscriber No. 56. It will be assumed in this instance that the main exchange subscriber called subscriber No. 56, in which case he gets the busy signal, as previously described, if the recorders are busy or if the called subscriber is busy, this signal being a tone which is transmitted over the speaking circuit leads. If a recorder is free, the connection is extended to the called subscriber and if he is free a speaking circuit may be traced as follows: conductors 381, contact 383, condenser 413, contact 408, contact 405, conductor 407, wiper 376, contact 377, conductor 221, contact 215, conductor 214, condenser 252, contact 341, contact 338, conductor 327, contact 328, wiper 317, contact 329, conductor 301, called subscriber's instrument, conductor 302, contact 330, wiper 318, contact 331, conductor 324, contact 340, condenser 414, conductor 224, contact 223, con-

ductor 222, contact 378, wiper 379, conductor 409, contact 404, contact 415, condenser 416, contact 384, conductor 382. This circuit extends to the main exchange in a manner which will be readily understood from the further description given hereinafter and the subscribers can now converse. When they have finished talking they hang up their receivers and battery is removed from across the conductors 381 and 382 at the main exchange, thereby permitting relay DRM to deenergize. Relay DRM releases and opens a circuit of RMT, which also releases; relay DRM also opens contact 408 permitting the relay LRT of the trunk relay group TRG to release and the trunk relay group TRG then releases as previously described. Relay RMT opens the circuit of relay COM, permitting this relay to release and the connection is thus restored to normal.

A description will now be given of the arrangements at the main exchange by which calls can be received from or extended to the sub-exchange. In Fig. 12 a diagrammatic layout is shown of the switches at the main exchange in connection with which a general understanding of the setting up of connections can be obtained.

When a call is received from the sub-exchange over a trunk line such as TL it is extended from the relay group ERTG to the trunk line switch TLS which has access to first selectors in a manner similar to the subscriber's line switch SLS. Consequently the trunk line switch is adapted to hunt automatically to find an idle first selector, for example D, in readiness for the reception of impulses corresponding to the first digit of the called main exchange subscriber's number. The setting up of a call is thereafter identical with the setting up of a call by a main exchange subscriber. The first digit is received on the first selector D which is stepped to the corresponding level and then hunts automatically to find an idle second selector such as E. The second selector E responds to the second digit and then hunts automatically to find a connector such as F. The connector F responds to the next two digits to establish connection with the line of the wanted main exchange subscriber. The operation of testing whether the wanted line is engaged or free, of signalling the called subscriber and closing the speaking circuit takes place in the well-known manner.

Assuming a main exchange subscriber desires access to a sub-exchange subscriber, then on lifting his receiver, his line switch SLS automatically operates to select an idle first selector such as D. The first two series of impulses operate the switches D and E respectively as before. The second selector E then hunts automatically to find an idle trunk line such as TL extending to the sub-

exchange. Associated with the trunk line in addition to the relay group ETRG is a battery feed group BFG by which the calling subscriber's impulses which consist of closing a loop feed with battery from the main exchange back to the calling subscriber's line are converted into impulses which consist of feeding battery forwards to the sub-exchange both initially on seizure and subsequently during impulse transmission and afterwards. The circuits by which the above operations are enabled to take place will be described with reference to Figs. 11 and 13.

Assume that a sub-exchange subscriber wishes to call a main exchange subscriber, then he first dials 0 as previously described, whereupon he is connected through to the trunk line whose conductors are referred to as 381, 382 and as described he feeds battery thereover prior to the transmission of impulses corresponding to the number of the wanted main exchange subscriber. A circuit is then completed as follows: battery, upper winding of retard coil RCM (Fig. 10), contact 387, contact 385, conductor 381 of trunk line TL, contact 500, relay DRE, contact 501, conductor 382, contact 386, lower winding of retard coil RCM to earth. Relay DRE energizes in this circuit and closes contacts 502 and 503, thereby completing a circuit for release relay RRE and preparing a circuit for relay LRE. Release relay RRE energizes and closes contacts 504, 505, 506. At contact 504 it prepares a circuit for relay CRE. At contact 505 it places earth on conductor 507 to guard the trunk line from being seized by a switch such as E and at contact 506 it completes a circuit for relay LRE as follows: battery, relay LRE, contact 508, contact 506, contact 509, retard coil RCE, contact 502, contact 510 to earth. Relay LRE energizes and closes contacts 511, 512. At contact 511 it connects the test wiper 513 to the magnet ME over the following circuit: wiper 513, contact 514, contact 511, interrupter contact 515, magnet ME to battery. If the first selector tested is busy, the contact 516 on which wiper 513 is resting will be connected to earth and the magnet ME will advance the wipers 513, 517, and 518 one step. This will continue as long as the selectors tested are busy.

It will be assumed that the selector D is idle consequently there will be no earth on contact 516. Accordingly relay COE will be energized in the following circuit: earth, contact 512, winding of relay COE, interrupter contact 515, magnet ME to battery. Relay COE, owing to its high resistance, alone energizes in this circuit and opens contacts 508 and 510 thereby disconnecting the line relay LRE and closing contact 521 thereby disconnecting the test wiper 513 from the magnet ME and connecting it to earth at contact 512 so as to mark the selector D busy during the interval which elapses before the release re-

lay in the selector D energizes. Relay COE also closes contacts 519 and 520 thereby extending the line circuit through to the first selector, the line relay of which energizes due to the closed circuit already described through retard coil RCE. The release relay of the selector energizes in a manner well known in the art and connects earth to test contact 516, thereby rendering the first selector busy and providing a holding circuit for relay COE as follows: earth on contact 516, wiper 513, contact 521, relay COE, interrupter contact 515, magnet ME to battery. This circuit is completed before relay LRE falls away and opens contact 512.

The series of impulses corresponding to the first digit in the wanted subscriber's number are now transmitted. As already described, the battery fed forward over conductors 381 and 382 of the trunk line TL is intermittently interrupted and relay DRE falls back for each impulse. In doing so it opens contact 502 thereby opening the circuit of the line relay of selector D in a similar manner to the interruption of the line circuit when a calling subscriber operates his calling device. Relay DRE also closes contact 522 and thereby completes a circuit for relay CRE as follows: earth, contact 522, contact 504, relay CRE to battery. Relay CRE energizes and closes contact 523, thereby completing a circuit across the wipers 518 and 517 independent of retard coil RCE as follows: wiper 517, contact 520, contacts 502, 523, 506, 519, wiper 518, so that the impedance of the impulsive circuit during dialling is reduced to a minimum.

The remaining series of impulses are repeated in a similar manner to the second selector E and the connector F and the connection is completed in the well-known manner if the called subscriber is free, and a busy signal is given if the called subscriber is busy. To release, as already described, battery is removed from across conductors 381, 382 when the calling subscriber restores his receiver and accordingly relay DRE deenergizes. Relay RRE also deenergizes, while the opening of contact 502 releases the switches TLS, D, E, and F. Relay RRE opens contact 505 and so renders the trunk line TL accessible to main exchange subscribers.

It will now be assumed that a main exchange subscriber requires a subscriber in the sub-exchange. The transmission of the first two digits operates a first and a second selector in the well-known manner, from the second selector access is had to trunk lines such as TL and it will be assumed that TL is the first one of a group found idle. Accordingly it will be assumed that the wipers 524, 525 and 526 respectively connected to conductors 530, 507 and 532 respectively which lead to the battery feed group BFG (Fig. 11). A cir-

cuit is then completed for relay LRB as follows: battery, upper winding of relay LRB, conductor 530, contact 527, wiper 524, through the selectors E and D and the subscriber's loop to wiper 526, contact 529, conductor 532, lower winding of relay LRB to earth. Relay LRB energizes and closes contacts 533 and 534 thereby completing a circuit for relay RRB and closing a point in a circuit to be completed later as will now be described.

Relay RRB on energizing closes contact 535 thereby connecting earth to conductor 507 which extends backwards to contact 528 to render the trunk line TL inaccessible, the earth potential also extends forwards to Fig. 13 completing a circuit for relay TRE which may be traced as follows: earth, contact 535, conductor 507, contact 536, relay TRE, relay COE, contact 515, magnet ME to battery, relays COE and TRE alone energize in this circuit. The operation of relay COE however is of no effect as relay TRE opens contacts 500 and 501, thereby disconnecting relay DRE and so prevents contacts 506 and 502 from closing and extending a circuit through the switch TLS. At contacts 537 and 538 relay TRE transfers the trunk line connection from relay DRE, to the conductors 539 and 540 so that battery is now fed to the sub-exchange over the following circuit: battery, upper winding of relay RCB, conductor 539, contact 537, conductor 381 to the sub-exchange, winding of relay DRM, to the main exchange over conductor 382, contact 538, conductor 540, contact 534, lower winding of retard RCB to earth. This therefore causes the relay DRM at the sub-exchange to energize, with the results already mentioned.

During impulsive of the next two digits which correspond to the number of the subscriber in the sub-exchange, relay CRB energizes over contacts 541 and 542 on the first impulse, remains energized throughout an impulse series and short-circuits the lower winding of retard RCB at contact 543 so as to increase the efficiency of the impulse series.

What is claimed is:

1. In a telephone system, a plurality of lines, a plurality of link circuits each having inductively coupled incoming and outgoing sections, a source of potential connected to each of said sections, and non-numerical switching means for interconnecting any of said lines and either end of any of said link circuits, said means including means responsive to the initiation of a call over any line for connecting that line to one section of an idle link circuit and means for connecting any particular desired line to the other section of the same link circuit.

2. In a telephone system, a plurality of lines, each terminating in a rotary lineswitch, each of said line switch banks being divided

- into two portions, a plurality of link circuits, each having incoming and outgoing sections, the incoming section of each link being connected to one of the bank portions of each of the lineswitches and the outgoing section of each link being connected to the other bank portion of each lineswitch, means in each lineswitch effective responsive to the initiation of a call over the associated line for causing the switch to hunt in one portion of its bank for an idle link circuit, and means for causing a particular lineswitch to hunt in its other bank portion for the other end of the same link circuit. 5
3. In a telephone system, a plurality of lines each terminating in a rotary lineswitch, each of said lineswitch banks being divided into two portions, a plurality of battery feed means each having inductively coupled incoming and outgoing sections, the incoming sections being connected to one of the bank portions of each of the lineswitches, and the outgoing sections being connected to the other bank portion of each of said lineswitches, 10 means in each lineswitch effective responsive to the initiation of a call for causing the associated lineswitch to hunt in one portion of its bank for an idle battery feed means, and means for causing the lineswitch of any particular line to hunt in the other portion of its bank for the opposite end of the same battery feed means. 15
4. In a telephone system, a plurality of lines, a plurality of link circuits each having inductively coupled incoming and outgoing sections, a source of potential connected to each of said sections, means responsive to the initiation of a call over any line for connecting that line to the incoming section of an idle link circuit, a numerical switch, means responsive to the establishment of said connection for connecting said numerical switch to the established connection, means controlled by the numerical switch for connecting the opposite end of said connected link circuit with any desired line, and means for disconnecting said numerical switch while retaining said other previously established connections. 20
5. In a telephone system, a line having a lineswitch individual thereto, a plurality of link circuits accessible to said lineswitch, and means for operating said lineswitch to seize an idle one of said link circuits at random to initiate a call outgoing from said line and for operating said lineswitch to seize any particular one of said link circuits to complete a call incoming to said line, said lineswitch being arranged to seize any given link circuit through one set of terminals to initiate a call, and through a different set of terminals to complete a call. 25
6. In a telephone system, a plurality of link circuits each having incoming and outgoing sections, a plurality of lineswitches, the in- 30
- coming sections of each of the link circuits being multiple connected to all of the lineswitches, and the outgoing sections of each of the link circuits being also multiple connected to all of said lineswitches, and means in each lineswitch for causing the lineswitch to seize any idle link circuit over the incoming end to initiate a call and to seize the outgoing end of a particular link circuit to complete a call. 70
7. In a telephone system, a plurality of link circuits each having inductively coupled incoming and outgoing sections, a source of potential connected to each of said sections, a plurality of lineswitches, the incoming and outgoing sections of each of the link circuits being multiple connected to all of the lineswitches, and means for causing any lineswitch to hunt for and seize the incoming section of an idle link circuit to initiate a call and to seize the outgoing section of a particular link circuit to complete a call. 75
8. In a telephone system, a link circuit having incoming and outgoing sections, a lineswitch having access to both of said sections, and means for causing the lineswitch to seize the incoming section to initiate a call and to seize the outgoing section to complete a call. 80
9. In a telephone system, a link circuit having incoming and outgoing sections, a line terminating in a lineswitch, each of said sections being connected to the bank of the lineswitch, a numerical switch, and means in the lineswitch effective responsive to the initiation of a call for causing the lineswitch to seize the incoming end of said link circuit and effective under the control of the numerical switch for causing the lineswitch to seize the outgoing end of the link circuit. 85
10. In an automatic telephone system, a plurality of lines, a plurality of link circuits each for interconnecting lines, means responsive to the initiation of a call for interconnecting the calling line and one end of an idle link circuit, a common numerical switch, means responsive to the establishment of said connection for exclusively associating the numerical switch with said established connection, means controlled by the switch for selecting a desired line, means immediately effective responsive to said selection for releasing the numerical switch, and means in said link circuit for indicating to the calling party the busy condition of the selected line. 90
11. In an automatic telephone system, a plurality of lines, a plurality of link circuits, each for interconnecting lines, means responsive to the initiation of a call for interconnecting a line and one end of an idle link circuit, a numerical switch, means responsive to the establishment of said connection for exclusively associating the numerical switch with said established connection, means controlled by the switch for selecting a desired line, means immediately effective responsive to said selection for releasing the numerical switch, and means in said link circuit for indicating to the calling party the busy condition of the selected line. 105
12. In an automatic telephone system, a plurality of lines, a plurality of link circuits, each for interconnecting lines, means responsive to the initiation of a call for interconnecting a line and one end of an idle link circuit, a numerical switch, means responsive to the establishment of said connection for exclusively associating the numerical switch with said established connection, means controlled by the switch for selecting a desired line, means immediately effective responsive to said selection for releasing the numerical switch, and means in said link circuit for indicating to the calling party the busy condition of the selected line. 110
13. In an automatic telephone system, a plurality of lines, a plurality of link circuits, each for interconnecting lines, means responsive to the initiation of a call for interconnecting a line and one end of an idle link circuit, a numerical switch, means responsive to the establishment of said connection for exclusively associating the numerical switch with said established connection, means controlled by the switch for selecting a desired line, means immediately effective responsive to said selection for releasing the numerical switch, and means in said link circuit for indicating to the calling party the busy condition of the selected line. 115
14. In an automatic telephone system, a plurality of lines, a plurality of link circuits, each for interconnecting lines, means responsive to the initiation of a call for interconnecting a line and one end of an idle link circuit, a numerical switch, means responsive to the establishment of said connection for exclusively associating the numerical switch with said established connection, means controlled by the switch for selecting a desired line, means immediately effective responsive to said selection for releasing the numerical switch, and means in said link circuit for indicating to the calling party the busy condition of the selected line. 120
15. In an automatic telephone system, a plurality of lines, a plurality of link circuits, each for interconnecting lines, means responsive to the initiation of a call for interconnecting a line and one end of an idle link circuit, a numerical switch, means responsive to the establishment of said connection for exclusively associating the numerical switch with said established connection, means controlled by the switch for selecting a desired line, means immediately effective responsive to said selection for releasing the numerical switch, and means in said link circuit for indicating to the calling party the busy condition of the selected line. 125
16. In an automatic telephone system, a plurality of lines, a plurality of link circuits, each for interconnecting lines, means responsive to the initiation of a call for interconnecting a line and one end of an idle link circuit, a numerical switch, means responsive to the establishment of said connection for exclusively associating the numerical switch with said established connection, means controlled by the switch for selecting a desired line, means immediately effective responsive to said selection for releasing the numerical switch, and means in said link circuit for indicating to the calling party the busy condition of the selected line. 130

switch, means in said link circuit for indicating to the calling party the busy condition of the selected line if the line is busy, and signalling means for signalling the called line if the line is idle.

5 12. In a telephone system, a link circuit having incoming and outgoing sections, a plurality of lineswitches, each of said sections being multiple connected to the bank of each 10 lineswitch, a numerical switch, means in each lineswitch responsive to the initiation of a call over the associated line for establishing a connection to an idle link circuit, means for exclusively associating said numerical switch 15 with the established connection, means controlled by the numerical switch for selecting a desired line, means responsive to the completion of the selection for releasing the numerical switch, means in the link circuit 20 thereafter effective for projecting signalling current to the selected line, and means in the link circuit for opening the signalling circuit responsive to the answering of the call.

13. In a by-pass telephone system wherein 25 connections between called and calling lines are established over link circuits by non-numerical switching mechanism under the control of a common numerical switch which is arranged to be used temporarily to control 30 the operation of the non-numerical switching mechanism, means for automatically releasing said numerical switch responsive to the selection of the called line regardless of the busy or idle condition of the called line, and 35 signalling means thereafter effective to signal the called line if the line is idle.

14. In a telephone system, a plurality of 40 lines each having a lineswitch individual thereto, a plurality of link circuits each including inductively coupled incoming and outgoing sections and battery feed means for each section, an impulse controlled line selecting device, means responsive to the initiation of a call over a line for operating 45 the associated lineswitch to connect the line with the incoming end of an idle link circuit, means for associating the line selecting device with the selected link circuit, and means controlled by the line selecting device for 50 selecting a particular lineswitch depending upon the digit dialled and for causing the selected lineswitch to hunt for and seize the other end of the associated link circuit.

15. In a telephone system, a plurality of 55 lines each having a lineswitch individual thereto, a plurality of link circuits each including inductively coupled incoming and outgoing sections and battery feed means for each section, an impulse controlled line selecting device, means responsive to the initiation of a call over a line for operating the associated lineswitch to connect the line with the incoming end of an idle link circuit, means for associating the line selecting device 60 with the selected link circuit, means con-

trolled by the line selecting device for selecting a particular lineswitch depending upon the digit dialled and for causing the selected lineswitch to hunt for and seize the other end of the associated link 70 circuit, means responsive to the seizure of the outgoing end of the link for releasing the line selecting device, and means responsive to the termination of the call for releasing the link circuit.

75 16. In a by-pass telephone system, a plurality of link circuits having inductively connected incoming and outgoing sections, a plurality of lines, non-numerical switching means for connecting a calling line to the incoming end of one of said link circuits, a numerical switch common to said link circuits, means for associating said numerical switch with said link circuit during the establishment of the connection, and non-numerical switching means controlled by said numerical switch for connecting the called line to the outgoing end of said link circuit.

80 17. In a by-pass telephone system, a plurality of link circuits having incoming and outgoing sections, non-numerical switching means for establishing a connection between a calling and called line over one of said link circuits, a numerical switch temporarily associated with said link circuit to 85 control said non-numerical switching means in the establishment of said connection, and means for releasing said numerical switch responsive to the selection of the called line regardless of the busy or idle condition of 90 said called line.

95 18. In a telephone system, a plurality of local line switches, a plurality of trunk line switches, and a plurality of link circuits, each having incoming and outgoing sections, 100 said incoming sections being multiply connected to the banks of said local and said trunk line switches and said outgoing sections being multiply connected to the banks of said local line switches only.

110 19. In a telephone system, a plurality of link circuits having incoming and outgoing sections, a plurality of local lines terminating in line switches which have access to both sections of said link circuits, and a plurality 115 of trunk lines terminating in line switches which have access to only the incoming sections of said link circuits.

120 20. In a telephone system, subscribers' lines each having a line switch individual thereto, a trunk line terminating in a line switch, a plurality of link circuits having incoming and outgoing sections, means responsive to the initiation of a call over one of said lines for operating the associated line switch to seize the incoming section of one of said link circuits, means responsive to the dialling of the subscriber's number for causing the line switch of the called line to seize the outgoing section of said link circuit, and 125 130

- means responsive to the dialling of the number designating said trunk line for causing the line switch of said trunk line to seize the incoming section of said link circuit.
- 5 21. In a telephone system, subscribers' lines, a trunk line, a link circuit having incoming and outgoing sections, means responsive to the initiation of a call for connecting the calling line to the incoming section of said link circuit and means temporarily associated with said link circuit and responsive to the dialling of the called number for connecting a called one of said lines or said trunk line to said link circuit, said called line being 10 connected to the outgoing section and said trunk line being connected to the incoming section of said link circuit.
22. In a telephone system, subscribers' lines, a trunk line, a plurality of link circuits 20 having incoming and outgoing sections, means for connecting a calling line to the incoming section of one of said link circuits, means responsive to the dialling of a subscriber's number for connecting the called 25 line to the outgoing section of said link circuit, and means responsive only to one particular digit dialled for connecting said trunk line to the incoming section of said link circuit.
- 30 23. In a telephone system, subscribers' lines, a trunk line, a plurality of link circuits having incoming and outgoing sections, means for connecting a calling line to the incoming section of one of said link circuits, 35 a numerical switch temporarily associated with said link circuit during the establishment of a connection, and means controlled by said numerical switch responsive to the dialling of the called number and dependent 40 upon the value of the digits dialled for connecting a called line to the outgoing section of said link circuit or for connecting said trunk line to the incoming section of said link circuit.
- 45 In witness whereof, I hereunto subscribe my name this 17th day of April, A. D. 1928.
RUDOLPH FRANK STEHLIK.
